MACHINES FOR SHAPING UPPERS OVER LASTS

Sidney J. Finn, Beverly, Mass., assignor to United Shoe Machinery Corporation, Flemington, N.J., a corporation of New Jersey

Application July 11, 1957, Serial No. 671,218

51 Claims. (Cl. 12—8.5)

This invention relates to machines for shaping uppers over lasts and is more particularly concerned with improvements in a machine for lasting the entire foreparts of shoes of the type disclosed in United States Letters Patent No. 2,703,420, granted March 8, 1955, on an application filed in the name of the present inventor. It will be understood, of course, that in certain broader aspects various features of this invention are not limited to use in a machine of the aforementioned type or to the exact mechanical construction shown.

As will be seen by reference to the aforementioned patent, the prior machine therein disclosed is intended for use in the lasting of shoes the uppers of which have not been previously subjected to a pulling over operation and in some respects, at least, is especially adapted for use on shoes having unlined uppers, the lasting margins of which are secured by cement to an insole on the last in the course of the lasting operation. Thus, the prior machine which has means for supporting a last in position for the shaping of an upper thereover, including displaceable shoe rest members, is also provided with a plurality of grippers for pulling the upper in different locations around the forepart of the last and comprising an end gripper for pulling the upper at the extreme toe end of the last, a plurality of toe grippers for pulling the upper at the opposite sides of the toe end of the last, and a plurality of forepart grippers for pulling the upper at the opposite sides of the forepart of the last, toe embracing forepart wipers for wiping the lasting margin of the upper inwardly over the bottom of the forepart of an insole on the last, and a pair of ball lasting units arranged to operate, respectively, in locations at the opposite sides of the ball portion of the shoe and each including a gripper for pulling the upper and wipers for wiping the upper inwardly over the insole in these locations. During the operation of the forepart grippers and wipers, the last is held against movement in a heelward direction by means of a heel rest, arranged to engage the upper at the heel end of the last and adapted also to locate the heel end of the last laterally in the machine, and the last is supported against heightwise movement by means of a toe pad arranged to engage the upper on the toe end of the last while a flexible toe band is provided for clamping the upper around the forepart of the last after the upper has been pulled over the last by the forepart grippers and prior to release of the upper by the forepart grippers for the wiping of the lasting margin of the upper inwardly over the insole by the forepart wipers.

As is further explained in the mentioned patent, the forepart grippers, except the toe end gripper, are initially positioned with their jaws spaced outwardly away from the lateral periphery of a last placed on the supporting means and are moved inwardly into engagement with the lateral periphery of the last prior to the insertion of the lasting margin of the upper therebetween. Subsequently, the jaws of these grippers are closed and the grippers are moved heightwise of the last to pull the upper over the last, whereupon, after the toe rest and toe band

2

have been moved into engagement with the upper at the forepart of the last and after the forepart grippers have been opened and retracted, the ball lasting units are operated to pull the upper at the opposite sides of the ball portion of the last and to wipe the upper inwardly over the insole in these locations, following which the forepart wipers are operated to wipe the lasting margin of the upper inwardly over the bottom of the forepart of the insole, thereby completing the operating cycle of the machine.

The various operating elements of the prior machine are actuated by fluid pressure operated pistons under the control of valves operated by a plurality of cams on a cam shaft which is arranged to be rotated through a half turn, in 60° steps, in response to three successive depressions of one treadle, and to be rotated through a second half turn by means including a single revolution clutch in response to depression of a second treadle. Thus, in response to an initial depression of the first treadle, the forepart grippers, except the gripper at the extreme toe end of the last, are moved inwardly against the last and at the same time, a heel rest holder is moved into operative engagement with the heel rest, while a second depression of this first treadle causes the jaws of the forepart grippers to close on the lasting margin of the upper inserted therebetween by the operator, and a third depression of this treadle causes the forepart grippers to be moved heightwise of the last thereby to pull the upper over the last. Now, depression of the second treadle by the operator will effect rotation of the cam shaft through its final half turn, during which the operating cycle of the machine is completed automatically and the various operating elements, with the exception of the heel rest holder which the operator has to release manually, are returned to their original positions.

A principal object of the present invention is to provide a machine of the same general type as that mentioned above which, at the same time, is not only improved in operation but is also of considerably more simple and inexpensive construction. With this broad purpose in view and with especial reference to the operation of the forepart grippers to pull the upper over the last, the herein illustrated machine, which has a plurality of fluid operated toe grippers movable heightwise of the last for pulling the upper at the opposite sides of the toe portion of the last, is, in accordance with a feature of the invention, provided with means for causing these grippers also to move in directions extending lengthwise of the last in response to their heightwise movements. More particularly, the means for causing such lengthwise movements of the toe grippers comprise cams which are so shaped as to provide a graded movement of each of the several toe grippers on each side of the last which is proportioned in accordance with the location of the gripper relatively to the toe end of the last. In addition, the gripper operating means is so arranged, in accordance with still another feature of the invention, that the upper pulling movements of the toe grippers, which, as indicated above, are moved in directions extending heightwise and lengthwise of the last, are effected prior to the heightwise pulling movements of the forepart grippers.

Further to improve the operation of the machine, and especially the action of the forepart grippers, the herein illustrated machine is provided with means for positioning the forepart grippers lengthwise of the last in accordance with the size of the last. More particularly, the forepart grippers of which there are two for pulling the upper, respectively, at each of the opposite sides of the forepart of the last, are positioned by guide means and these guide means are actuated by means operable in response to the movement of an abutment member, i.e., the

heel rest, into engagement with the upper at the heel end of the last for effecting movements of the guide means which are so proportioned that the forepart gripper which is nearest to the toe end of the last is always positioned midway between the other forepart gripper and the rearmost toe gripper on that side of the last.

With the view especially of simplifying the construction of the machine, with particular reference to the operating and control mechanism thereof, in the herein illustrated machine, in accordance with additional features of the invention, the actions of the several operating elements, including the fluid pressure operated forepart grippers and wipers and the fluid pressure operated ball lasting units, which occur after the initiation of the operating cycle, in response to movement of a treadle operated control valve, are controlled by a plurality of sequence valves, and means under the control of these sequence valves are provided for returning the treadle operated control valve after the operation of the grippers and wipers to complete the automatic operating cycle of the machine. More particularly, the herein illustrated machine has two treadle operated control valves, one of which effects inward movement of the forepart grippers, while the other initiates the operating cycle of the machine, and fluid pressure operated means under the control of one of the sequence valves are provided for automatically returning the two treadle operated valves after the operation of the grippers and wipers to complete the operating cycle of the machine.

As has been indicated above, in the herein illustrated machine, the operating cycle is initiated in response to the depression of a treadle operated control valve, and during this operating cycle, which is controlled by a plurality of sequence valves, various actions of the operating elements are effected, including, among others, the wiping of the lasting margin of the upper inwardly over the bottom of the forepart of the insole on the last. Inasmuch as the operator will have inserted the lasting margin of the upper into the open jaws of the forepart grippers just prior to his depression of the treadle for initiating the operating cycle, it is quite possible that one or the other of his hands may remain on, or near the shoe in a position to be injured by the forepart wipers as they are advanced and closed. In order to avoid such an accident, and also to afford an inspection dwell in the operating cycle, the herein illustrated machine is provided with a cycle interrupting valve which is adapted to be set for discontinuing the flow of fluid under pressure to certain of the sequence valves for interrupting the operating cycle, together with operator controlled means for actuating the cycle interrupting valve to reestablish the flow of fluid under pressure to said sequence valves, thereby to continue the operating cycle. More particularly, this cycle interrupting valve is adapted to be set in response to the operation of the first treadle operated control valve referred to above for discontinuing the flow of fluid under pressure to certain of the sequence valves for interrupting the operating cycle, prior to the operation of the forepart wipers, while the operator controlled means for actuating the cycle interrupting valve comprises two control members located, respectively, at the opposite sides of the last supporting means and adapted to be engaged by the hands of the operator as they are moved outwardly away from the shoe.

The above and other objects and features of the invention, including an improved heel rest operating and locking mechanism and novel means for guiding the upper materials into the open jaws of the ball grippers, will appear in the following detailed description of the preferred embodiment thereof which is illustrated in the accompanying drawings, and will be pointed out in the claims.

In the drawings—

Fig. 29 is a view in vertical section substantially on line XXIX—XXIX of Fig. 27 and looking in the direction of the arrows;

Fig. 30 is a view in vertical section substantially on line XXX—XXX of Fig. 27 and looking in the direction of the arrows;

Fig. 31 is a view in vertical section substantially on line XXXI—XXXI of Fig. 20 and looking in the direction of the arrows;

Figs. 32, 33 and 34 are a series of three views in vertical section extending longitudinally through the toe end of a shoe being lasted and illustrating different positions assumed by various operating elements during operation of the machine;

Fig. 35 is a plan view of the lower portion of the machine and showing the location and arrangement of certain of the parts of the fluid pressure operating system of the machine;

Fig. 36 is a view of a portion of the machine, with certain parts in vertical section and others omitted to simplify the disclosure, illustrating the location and arrangement of two manual levers provided for controlling the operation of the machine;

Fig. 37 is a view in vertical section of one of the several sequence valves used in the fluid pressure operating system;

Fig. 38 is a view in vertical section substantially on line XXXVIII—XXXVIII of Fig. 35 and looking in the direction of the arrows of one of the control valves of the fluid pressure operating system;

Fig. 39 is a view in vertical section substantially on line XXXIX—XXXIX of Fig. 35 and looking in the direction of the arrows of another valve forming a part of the fluid pressure operating system;

Fig. 40 is a view in vertical section, substantially on line XI—XL of Fig. 35 and looking in the direction of the arrows of still another valve forming a part of the hydraulic system; and

Fig. 41 is a schematic drawing illustrating the fluid pressure operating system and showing the various operating elements of the machine diagrammatically.

Referring to these drawings, and particularly to Fig. 3 thereof, the operating elements of the machine therein disclosed comprise a plurality of grippers all of which may be termed generally forepart grippers for pulling the upper in different locations around the toe end and at the opposite sides of the forepart of the last and including an end gripper 100 for pulling the upper at the extreme toe end of the last, three toe grippers 102, 103 and 104 for pulling the upper at each of the opposite sides of the toe end of the last, and two forepart grippers 105 and 106 for pulling the upper at each of the opposite sides of the forepart of the last; a pair of forepart wipers 110, Fig. 27, for wiping the lasting margin of the upper inwardly over the bottom of the forepart of an insole on the last; a pair of so-called ball lasting units arranged to operate, respectively, at the opposite sides of the ball portion of the shoe, including locations where the edge of the shoe bottom curves inwardly toward the shank beyond the ball line, and each comprising a ball gripper 112 and two ball wipers 114 and 116; and a flexible toe band 118, Figs. 19 and 21, arranged to be applied around the toe and along the sides of the forepart to clamp the upper against the last prior to the release thereof by the forepart grippers. During the operation of the forepart grippers, the last is supported and positioned heightwise by means of a plurality of shoe rest members 120, 122, 124, 126 and 128 which are displaceable inwardly from the edge of the bottom of the shoe as the upper materials are wiped inwardly over an insole on the last by the forepart wipers, while four yieldable insole holdowns 130, 131, 132 and 133 hold the insole down against the bottom of the last to prevent displacement of the insole by

the wipers. Further to support the shoe in a heightwise direction against the action of the forepart wipers, a toe pad 134, see Figs. 19, 21, 33 and 34 is provided, while a heel rest 136, see also Fig. 12, movable from a remote position into engagement with the upper at the heel end of the last, serves to hold the last against lengthwise movement in a heelward direction, from a position determined by a toe gage 140, Figs. 4, 32 and 33, during the operation of the forepart wipers and also serves to locate the heel end of the last laterally in the machine.

These several operating elements and supporting members are associated with a frame construction indicated generally by the reference character 150 and the operating elements are actuated by fluid operated pistons the actions of which are controlled by various control and sequence valves to be referred to in detail below, this fluid pressure system being for the most part contained within the lower portion of the frame construction, as will be apparent from Fig. 1 of the drawings. For controlling the action of the machine prior to the beginning of an automatic operating cycle and for initiating such automatic operating cycle, a pair of foot treadles 152, 154, Figs. 1 and 2, and a pair of hand levers 156, 158, see Fig. 3, are provided.

Supported on an upper portion 160 of the frame construction by means of curved arms 162, 162, Figs. 1 and 4, is a cylinder block 164 to the upper side of which there is secured a post 166. At its extreme upper end 168 this post is reduced in size and is of generally square cross

30 section so as to slidably support a retarder member 170 which is yieldably mounted on coil springs 172, 172, received within counter bores 174, 174 in the retarder and engaging thrust flanges 176, 176 formed on rods 178, 178, Figs. 5 and 6. At their lower ends, the rods 178, 35 178 bear on an adjusting plate 180 having several stepped surfaces 182, 182 for engaging the rods when the plate is lifted off of locating pins 184, 184 and moved to different positions by means of a finger tab 186. Threaded through a rearward projection 188 on the upper portion

40 168 of the post 166 is a stop screw 190, Fig. 5, and normally in engagement with this screw, to hold the retarder in place on the upper portion of the post, is a latch block 192 which is pivotally mounted on the retarder by means of a pin 194 and urged into latching position by a spring 45 196. The retarder is cut away, as indicated at 198, to provide a generally U-shaped operating surface 200, and pivotally mounted on a pin 202, carried by ears 204 formed on a member 206 adjustably mounted on the upper portion of the post, is the shoe rest member 120, referred to above. As is shown in Figs. 4 and 6, see also Figs. 32 and 33, the toe gage 140, previously mentioned, is slidably mounted in the front portion of the retarder 170 and formed on this toe gage is a hook-like portion 208 which is adapted to hold the shoe rest member 120 in the upright position in which it is shown in Figs. 4 and 32 when the toe gage is elevated.

45 The other two shoe rest members 122 and 124 are each associated, respectively, with a carrier 210 on which one of the ball lasting units is mounted, see Fig. 25 in which parts associated with the ball lasting unit on the right, as viewed in Fig. 3, are shown. Each of the carriers is slidably mounted on a plate 212, Fig. 26, secured to a frame member 214 by means of screws 215 and also to the post 166 by means of a screw 217, Fig. 25, and is held in place on the plate by means of a detachable gib 216. Mounted on the forward end of each of these gibs is an upright member 218, Fig. 25, and the shoe rest members 122 and 124 are pivotally mounted, respectively, on these upright members and held yieldingly in upright positions by springs 219. As will be

50 65 70 explained below, the ball lasting units are shifted toward and away from the toe end gripper 100 in order to accommodate right and left shoes, respectively, and the shoe rest members 122 and 124, mentioned above, as well as the two other shoe rest members which, as pres-

ently will appear, are carried by the ball lasting units, partake of these movements so as to be brought into proper locations for engaging the insole on the bottom of the last in the immediate vicinity of the ball portion thereof, see Fig. 3, and the broken-line outline of the shoe therein illustrated. The insole holddowns 130, 132 each comprise a coil spring 220 having a flattened end portion 222, Fig. 25, and carried by a block 224 which is secured to the forward end of an elongated slide 226. Each of these slides is guided for rectilinear sliding movement on the upper surface of one of the gibs 216 by means of a pin 230 and a groove 232 in the member 218 and is urged yieldingly to the right, Fig. 25, by means of a coil spring 234. The insole holddowns 131 and 132 each comprise a U-shaped spring 236, Fig. 5, mounted on pins 238, 240 carried by the retarder 170, these springs being held in place by means of plates 242, 244 secured to the retarder by screws 244.

The toe gage 140 is mounted for vertical sliding movement along a guideway 250 formed in the retarder 170, Fig. 6, and is normally held in its elevated and operative position, as shown in Fig. 4, by means of a spring 252. This spring bears against the upper end of a piston N fitted within a cylinder 256 which is secured to the post 168, referred to above. Formed integrally with this piston is a connecting rod 258 which is connected, by means of a pin and slot, to one end of a lever 260 pivotally mounted within a cross slot 262 formed in the aforementioned post 166. A link 264 extends between the other end of this lever and the lower portion of the toe gage. As will be apparent when fluid under pressure is admitted to cylinder 256 through a conduit 264, the toe gage 140 will be moved downwardly, see Figs. 33 and 34, thereby releasing the shoe rest member 120 for inward movement.

The heel rest which is indicated generally by the reference character 136 comprises a block 270 which is adjustably mounted, by means of a ratchet bar 272, ratchet teeth 274, and a clamp screw 276, on a base member 278, Fig. 12. This base member, in turn, is slidably mounted along guideways 280, 280, formed in a support 282, see also Fig. 3. This support is mounted for limited swinging movement in a direction extending laterally of the machine by means of arcuately shaped guide blocks 284, 284, secured to the upper face of a frame member 285, and received in correspondingly shaped grooves 286, 286 formed in the support. A pin 288, carried by the member 278 and having an enlarged upper end 290, Fig. 3, is adapted to be received in one or the other of two locating holes 292, formed in the frame member 285 and one which appears in Fig. 12, for holding the support 282 and heel rest block 270 in one or the other of two laterally adjusted positions for locating the heel rest to accommodate right or left shoes. In Fig. 3, the heel rest is set to receive a left shoe which is shown in outline by a broken line and indicated by the reference character Sh.

The heel rest block 270 is provided with a V-shaped recess 300 for engaging and locating the heel end of the shoe Sh placed on the shoe rest members 120, 122 and 124 with its toe end in engagement with the toe gage 140. The heel rest normally occupies a somewhat retracted position, see Figs. 3 and 12, and is moved upwardly and forwardly into engagement with the heel end of the shoe by means of a fluid pressure operated piston A. This piston is received within a cylindrical bore 302 formed in a cylinder 304 which is pivotally mounted on the frame member 285 by means of a pin 306. At an appropriate time in the operating cycle of the machine, as will be more particularly explained below, fluid under pressure is admitted to the cylindrical bore 302 through a passage 308, formed in the cylinder 304 and to which there is connected a flexible conduit 310. At its lower end, the piston A, Fig. 12, is connected to one arm of a lever 312 which is keyed to a cross shaft 314, journaled

in bearing brackets mounted on a part of the frame portion 160 and located on the opposite sides of a slot 316 therein through which the mentioned lever projects, one of these two bearing brackets appearing in Fig. 12 and being identified by the reference character 318. Extending between the other arm of the lever 312 and a downwardly projecting boss 320 on the base member 278 and connected to these parts by ball-and-socket joints is an operating link 322.

Located within the V-shaped recess 300 in the heel rest block 270 is a sensing arm 330 which is secured to a shaft 332 journaled in the block, Figs. 12 and 13. A coil spring 334 normally swings this arm in a clockwise direction and to the extent determined by a stop pin 336, Fig. 12. One end of the shaft 332 projects outwardly beyond one side of the block 270 and attached to this end of the shaft is an arm 337 which carries a pawl operating spring 338 bearing against two pawls 340, 340 rotatably mounted on the shaft 332, Fig. 13. These pawls are normally held out of engagement with locking teeth 342, formed on a metal strip 344 secured to the support 282, by means of a pin 346 carried by the arm 337 which engages upwardly extending portions 348 of these pawls. However, when the heel rest is moved to its operative position and into engagement with the heel end of a shoe, the sensing arm 330 will be swung in a counterclockwise direction thereby causing one or the other of the two pawls 340, 340 to engage the teeth 342 and lock the heel rest against downward and rearward movement away from the heel end of the shoe. As shown in Figs. 3 and 13, the pawls 340, 340 and associated parts are contained within a protective housing 350 which is secured to the heel rest block 270 by means of screws 352. At the end of the operating cycle, when

35 the lasted shoe is released and cylinder 304 is connected to exhaust, spring 334 will swing the sensing arm 330 in a clockwise direction, Figs. 12 and 13, thereby releasing the heel rest for return to its initial position by gravity.

As stated above, the forepart grippers include an end gripper 100, six toe grippers 102, 102, 103, 103, 104, 104, three on each side of the shoe being lasted, and four forepart grippers 105, 105, 106, 106, two on each side of the shoe. With the exception of the end gripper, which, as will appear below, has a novel double jaw arrangement, these forepart grippers are of similar construction and differ only in the exact manner in which they are controlled and positioned. Thus, each forepart gripper comprises a support indicated generally by the reference character 400 and comprising a pair of side plates 402, 404, Figs. 14 and 15, in which one of the toe grippers 104 is illustrated. At their lower ends, the two plates 402, 404 are secured to a separator block 406 which, in turn, is pivotally mounted by means of a pin 408 on the upwardly extending arm 418 of a lever 412 having a laterally extending arm 414. The lever 412 is pivotally mounted by means of a pin 416 on a housing 420 which is formed integrally on the upper end of a hollow plunger 422, see also Fig. 4. As is illustrated in Fig. 14, a compression spring 424 is arranged to bear against the arm 414 of the lever 412 and holds this arm yieldingly against a stop pin 426. Each of the plungers 422 is of rectangular cross sectional shape and is received within a correspondingly shaped guideway 430 formed in the cylinder block 164, see Fig. 8, wherein in the particular gripper with which each plunger is associated is designated by its proper reference character in parentheses.

At their upper ends, the side plates 402, 404 of each forepart gripper are secured to a gripper body portion 440 having formed integrally therewith a cylinder 442, Fig. 14, closed at one end by a cover 444. Slidably mounted in this cylinder is a piston C provided with a piston rod 448 which carries at its end a roller 450, a compression spring 452 being arranged to hold the piston and roller in the positions in which they are

shown in Fig. 14 and with the piston C bearing against the cover 444, when the cylinder 442 is connected to exhaust through a conduit 454. Pivotally mounted on the gripper body 440 is a movable jaw 460 which is adapted to cooperate with a fixed jaw 462 formed integrally with the gripper body. As shown in Fig. 14, the outer and movable jaw 460 is provided with a smooth operating face 464, while the operating face of the inner or fixed jaw 462 is provided with a series of teeth 466. Secured to each gripper is a gage plate 468 which is arranged to determine the distance the lasting margin of the upper materials may be inserted within the open jaws of the gripper. A coil spring 456 is arranged to hold the outer jaw 460 in the open position in which it is shown and with a camming surface 458 against the roller 450. As will be apparent when fluid under pressure is admitted to the cylinder 442 through the conduit 454 the piston C will be moved upwardly and the roller 450 acting on the surface 458 will move the jaw 460 toward the jaw 462.

Referring to Figs. 4 and 8, there are mounted in the cylinder block 164 a plurality of cylinder sleeves 470 which are in communication at their lower ends with a manifold passage 472 formed in a header block 474, Fig. 9, which is secured to the lower side of the cylinder block 164. Slidable within each of these sleeves is a piston B to which there is secured a piston rod 476 which extends upwardly through an aperture in a cover plate 477. At their upper ends each of the piston rods 476 which is associated with a toe or a forepart gripper bears against the arm 414 of a lever 412, Fig. 14, while in the case of the end gripper 100, the piston rod 476 bears directly against a portion of the housing 420, Fig. 4. As will presently appear, when the machine is idle but with the fluid pressure system in operation, fluid under a relative light pressure is admitted to the manifold passage 472 through a conduit 478, Fig. 9, and the pressure of this fluid acting on the several pistons B holds the forepart grippers elevated to positions determined by the engagement of the upper sides of the several housings 420 with adjustable stop screws 480 carried by a U-shaped plate 482, Fig. 7. This plate is slidably received within grooves 484, 484 formed, respectively, in two head portions 486, 486 carried on the upper ends of two plungers 488, 488 which are mounted for vertical movement in cylindrical guide bores 490, 490 associated with the arms 162, 162, Fig. 8.

Secured to the lower side of the cylinder block 164, by means of a stud 500, nut 502, and a spacer block 504 through which the stud passes, is a lower cylinder block 506 provided with eleven cylinder bores 508, Fig. 10, each one of these bores being associated, respectively, with a particular forepart gripper, as indicated by the reference character in parentheses. Slidable in each of these cylinder bores is a piston D having an upwardly extending piston rod 510 and a downwardly extending stem 512, Fig. 4. At its upper end, each of the piston rods 510 carries an enlarged head 514 which slides within a bore 516 formed in a plunger 422, this bore being of reduced diameter for a short portion of its length in order to provide a shoulder 518 against which the head 514 may at times bear, Fig. 14, see also Fig. 17. As shown in Fig. 10, the cylindrical bores 508 which are associated with the end gripper 100, the two toe grippers 102, 102 and the two toe grippers 103, 103 are in communication with a manifold passage 520 formed in the block 506 and having a conduit 522 connected thereto. Similarly, the two cylindrical bores 508 which are associated with the two toe grippers 104, 104 are in communication with two conduits 524, 524, while the four cylindrical bores 508 which are associated with the four forepart grippers 105, 105 and 106, 106 are in communication with two manifold bores 525 to which there are connected conduits 526. During the operation of the machine, as will presently appear, fluid under pressure is

admitted first to the conduit 522, then to conduits 524, 524, and finally to the two conduits 526, 526 thereby causing the several pistons D to be actuated for effecting downward movement of the forepart grippers in a pre-determined sequence.

For limiting the downward movements of each of the pistons D thereby to determine the extent of movement of the associated grippers, there is located directly below each piston and in vertical alinement with its stem 512, an adjustable stop screw 530, see Fig. 4 and also Fig. 11, in the latter figure of which these stop screws are identified with their associated gripper by means of reference characters in parentheses. These adjustable stop screws are threaded through a plate 532 which is slidably mounted in grooves 534 formed in a U-shaped supporting member 536, Fig. 11. This supporting member is provided with spaced upstanding ears 538, 538, and is pivotally supported on a block 540 by means of a pivot pin 542, see also Fig. 4. The block 540 in turn is slidably mounted for vertical adjustment, by means of a hand nut 544 and lock nut 546, on an end portion 545 of the stud 500 and is held against rotation thereon by means of a keylike projection 548, formed integrally with a downwardly extending portion 550 of a bracket 552 and fitting within a keyway 554 formed on the block 540, Fig. 11. A longitudinally movable cam member 556 having an inclined cam surface 558 is slidably mounted in a groove 560, formed in the block 540 and is held in place therein by means of a cover plate 562. This cam member passes through a clearance slot 564 in the end portion 545 of the stud 500 and its inclined surface 558 supports the right-hand end of the U-shaped member 536 by engagement with a pin 568, Fig. 4. At one end the cam member 556 is connected, by means of a link 570, to a lever 572 which is pivotally mounted on a portion of the bracket 552 by means of a pin 574. Pivoted on this lever is a nut 576 through which there is threaded the lower end of an adjusting shaft 578, see also Fig. 10. This shaft extends upwardly to the front 40 of the machine, Fig. 2, and carries at its upper end a hand wheel 580, Fig. 1. As will be apparent, by rotating this hand wheel, the plate 532 may be swung about the axis of the pin 542 thereby to vary the heightwise positions of the several stop screws 530 relatively to each other, while all of these stop screws may be adjusted together and equally in a heightwise direction by means of the nut 544.

After the forepart grippers have been operated to seize and to tension the upper around the forepart of the shoe being lasted, the ball grippers are closed and actuated to tension the upper in the vicinity of the ball line on the opposite sides of the shoe and the toe band is brought into engagement with the upper around the toe end of the shoe, whereupon the forepart grippers are opened to release their grip and tend to drop by gravity. Immediately thereafter the ball wipers 114, 116 on each of the opposite sides of the shoe are operated and in order to assure that the forepart grippers 105, 106 on each side of the shoe are moved downwardly to a position out of the way of these wipers, the following arrangement is provided. As shown in Fig. 17, the sleeve 470 in which the piston B associated with each gripper 106 is fitted is closed at its upper end by means of a plug 590 through which the piston rod 476 projects. Also, at its upper end each of these two piston rods carries a pin 592 which is adapted to engage another pin 594 in the housing 420 when the piston B and rod 476 are moved downwardly, see also Fig. 18. In addition, each of the grippers 106 is provided with a laterally extending abutment member 596 which is in vertical alinement with and directly above one end of the pin 416 which is associated with the adjacent gripper 105, Fig. 16. Each of the plugs 590 is provided with a port 598 which is in communication with a manifold passage 600 formed in a header piece 602, Fig. 8, and connected to this manifold passage is a con-

duit 604. At an appropriate time in the operating cycle of the machine, and as will be explained in detail below, fluid under pressure is admitted through the conduit 604 to the space in each sleeve 470 above the piston B thereby causing these pistons to move downwardly and to pull the grippers 105 and 106 on each side of the machine downwardly and out of the way of the ball wipers.

Near the end of the operating cycle of the machine the forepart wipers 110, Fig. 27, are operated to wipe the lasting margin of the upper materials inwardly over the bottom of the forepart of the shoe and, in order to make certain that the forepart grippers 100, 102, 102, 103, 103 and 104, 104, which have previously been opened to release the upper material, are positively moved downwardly and out of the way of the advancing wipers 110, 110, the following arrangement is provided. As has been noted above, the plate 482 which carries the stop screws 480 is supported by two head portions 486, 486 mounted on the upper ends of two vertically movable plungers 483, 488, Figs. 7 and 8, and see also Fig. 4. At its lower end, each of the plungers 488 is connected, by means of a link 610, to one arm of a lever 612, pivotally mounted on a bracket 614 secured to the cylinder block 164, see Figs. 4 and 8. Connected to the other arm of each of these levers is a second and much longer link 616, see also Fig. 1, and at their upper ends, each of these longer links is connected to one arm of a lever 618, pivotally mounted on a bracket 620 associated with the portion 160 of the frame of the machine, Fig. 21. As will presently be explained, just prior to the operation of the forepart wipers, these two levers are swung, in a clockwise direction, Fig. 21, thereby causing the plungers 488 to descend and, by carrying the plate 482 downwardly, to move the aforementioned forepart grippers downwardly and out of the way of the advancing forepart wipers.

Referring to Fig. 14, each of the forepart grippers, with the exception of the end gripper 100, is held in the position in which it is shown in Fig. 3 of the drawings by the action of a spring 424 to swing the lever 412 in a counterclockwise direction and to the extent determined by the pin 426, and when the grippers are each in this position their inner or fixed jaws 462 are spaced outwardly from the marginal edge of the bottom of the last of a shoe placed in the machine to be lasted. Also, as will presently appear, when the machine is idle the several forepart grippers, including also the gripper 100, are held in the elevated position indicated in Fig. 4 of the drawings by fluid at a relatively low pressure admitted to the sleeves 470 beneath the pistons B through conduits 478, Fig. 9. At the beginning of the operating cycle, the pressure of the operating fluid in these sleeves is considerably increased and inasmuch as further upward movement of the grippers is prevented by the stop screws 480, the levers 412 will be rocked in a direction, by the piston B, to swing the grippers, with the exception of the gripper 100, inwardly toward the shoe until the inner jaw 462 of each gripper engages the side of the last.

As is shown in Fig. 4, the end gripper 100 is positioned relatively to the toe end of the last of the shoe in the machine by means of a roll 630 which rides in a cam track 632 formed in one of two plates 634, 634, Figs. 3 and 4, secured to a boss formed on the frame portion 160. As will be observed, this cam track is so shaped that when this gripper is in its uppermost position, Fig. 4, its inner or fixed jaw 462 is substantially in contact with the toe gage 140, see Fig. 32. Also, as this gripper is moved downwardly, the action of the roll 630, as it travels along the cam track 632, first swings the gripper away from the toe end of the last until a cut-away portion 636 on the cam track permits the gripper to assume a position determined solely by the pull of the upper materials thereon. This outward swinging movement of the end gripper 100 during its initial downward and pulling movement imparts a lengthwise component to the pull which is applied

to the upper material and, in order to permit, as well as to augment, the resulting lengthwise displacement of the upper materials relatively to the last, similar movements lengthwise of the last and toward its toe end are imparted to certain of the other forepart grippers.

As will be apparent from Fig. 1, the post 166 and other associated parts, including the several forepart grippers, are inclined from the vertical and toward the front of the machine so that the view shown in Fig. 4 of the drawings is not, strictly speaking, a vertical section but actually is a section on a vertical plane which has been swung in a clockwise direction to the position shown in Fig. 4 for the purpose of simplifying the disclosure. Because of the inclination of the post 166, each of the forepart grippers, except the end gripper 100 which is otherwise restrained in the manner just explained, would tend to swing about its associated pin 408, Fig. 14, under the influence of gravity. Such swinging movement of these grippers is, however, limited, and the grippers held in the positions in which they appear in Fig. 3 of the drawings, in the following manner. Referring to Figs. 25 and 26, each of the plates 212 on which the carriers 210 are mounted are provided with an upper and a lower guideway 640, 642, while opposite to each upper guideway 642 there is formed in the carrier 210 a matching guideway 644. Slidably mounted in each guideway 640 is an elongated bar 650 provided at its right-hand end, as viewed in Fig. 25, with three outwardly projecting guide fingers 652, 653 and 654, while somewhat similar guide fingers 655, 656 are associated, respectively, with two other elongated bars 658, 660 which are slidably mounted in the guideways 642, 644. As is shown in Fig. 3, these guide fingers are disposed at different angles, corresponding to the angular disposition of the several guide bores 430, Fig. 8, formed in the block 164 and which receive the several plungers 422, mentioned above. Also, it will be noted in Fig. 3 that the fingers 652, 653 and 654 are adapted to project in between the two side plates 402, 404 of its associated gripper, see Fig. 14, while the fingers 655 and 656 are adapted to bear against the outer surface of one of the side plates on its associated gripper.

Referring to Figs. 14 and 15 of the drawings, there is secured to the inner surface of each side plate 402 of the toe grippers 102, 103 and 104 a cam member 670 having upper and lower cam surfaces 672, 674. When the forepart gripper 104 shown in Fig. 15 is in its initial elevated position, its associated guide finger 654 is located directly beneath the cam surface 674 and the same is, of course, true with respect to the guide finger 654 associated with the other toe gripper 104 and the guide fingers 652, 653 which are associated with the toe grippers 102, 103 on each of the opposite sides of the shoe being lasted. Accordingly, when these grippers are moved downwardly to tension the upper materials previously seized thereby, as the cam surfaces 674 move downwardly over the several guide fingers 652, 653 and 654, a component of movement in a direction toward the toe end of the last of the shoe being lasted will be imparted to each of these grippers.

As suggested above, the inclinations of the several cam surfaces 674 are so selected as to provide a graded amount of movement of each toe gripper in a direction toward the toe end of the last, which movement is proportional to the location of the gripper relatively to the toe end of the last. In other words, the greatest amount of toeward movement is imparted to the toe grippers 104, 104, which are the greatest distance away from the toe end of the last, a smaller amount of movement is imparted to the toe grippers 103, 103 while a still lesser movement is imparted to the grippers 102, 102 which, of course, are closest to the toe end of the last. As will be noted in Figs. 14 and 15, a portion of the side plate 404 of each of the grippers is cut away as indicated at 676 so as to permit such

toeward movement of these grippers without interference of the guide fingers with the opposite side plate 404. During the aforementioned toeward movements of the several toe grippers 102, 103 and 104, and the toeward movement of the end gripper 100, mentioned above, the forepart grippers 105, 106 are free to move toewardly with the upper materials and away from their respective guide fingers 655, 656 in a manner which will be apparent from an inspection of Fig. 3. Because of this gathering action of the forepart grippers, the upper materials will be drafted lengthwise of the last and, at the same time, these materials will be shaped nicely to the forepart of the last without any tendency to or danger of the formation of pleats or wrinkles in the upper materials between adjacent grippers. In the latter connection, it will be recalled, as suggested above, that the forepart grippers are operated in a predetermined sequence with the end gripper 100 and the two forepart grippers 102, 103 on each side of the machine being caused to apply their pull to the upper materials first, followed next by the application of the pull applied by the toe grippers 104, 104 on opposite sides of the shoe, and then by the pull applied by the forepart grippers 105, 106 on the opposite sides of the shoe.

In order to position the two forepart grippers 105 and 106 which are located on the opposite sides of the machine in proper position to accommodate shoes of different sizes and rights or lefts, and also for moving the ball lasting units toward or away from the toe end of the shoe being lasted and for shifting these units relatively to each other for the same purposes, the following arrangement is provided. Each of the two carriers 210 is connected, by means of an adjustable stud 680, to one end of a link 682. At its other end, each of these two links is connected to a mid-point of a downwardly projecting arm 684 which has an enlarged portion 686 and an upper part provided with a ball-like end 688, Figs. 2 and 3, each of these arms being journaled at its lower end on the shaft 314 which is mentioned above. The enlarged portion 686 of each of these arms is provided with two spaced-apart bores 690 each adapted to receive a spring retained locking pin 692 carried by an arm 694 which is fast on the aforementioned shaft 314. As will be apparent, when the lever 312 is rocked to move the heel rest 136 into engagement with the heel end of a shoe placed in the machine, the shaft 314 to which this lever is connected will be turned, in a clockwise direction as viewed in Fig. 12, and as a result of such turning movement of this shaft, the links 682 and carriers 210 will be moved upwardly from the positions in which they are shown in Fig. 3 of the drawing and to an extent which is proportional to the size of the shoe. In addition, it will be understood that in order to accommodate rights and lefts, the pins 692, 692 may be withdrawn from the bores in the arms 684 and the positions of the arms 684, 684 relatively to the arms 694, 694, reversed.

Referring to Fig. 25, there is pivotally mounted, by means of a pin 698, on each of the supporting plates 212 an arm 700 which is provided with an elongated slot 702 having a widened portion 704 adjacent to its lower end. Projecting into the upper portion of this slot is a pin 706 mounted on an upper portion of the carrier 210. Accordingly, when the two carriers 210 are moved upwardly, Fig. 3, either as a result of the movement of the heel rest into engagement with the heel end of the shoe being lasted or when these carriers are shifted relatively to each other, by means of the arms 684, 684, the arms 700 will be swung in a clockwise direction, Fig. 25, and through an angle which is proportional to the amount of movement imparted to its associated carrier 210. Secured to the left-hand end of each of the bars 658 is an L-shaped plate 712 carrying at its lower end a pin 712 which projects into

the widened portion 704 of the slot 702, while the bar 660 carries a pin 714 which also projects into the upper portion of this slot. The spacing of the pins 712 and 714 lengthwise along the slot 702 is such that as the bars 658, 660, guide fingers 655, 656, and the associated forepart grippers 105, 106 are moved lengthwise of the shoe being lasted in accordance with the size of the shoe, as a result of movement of the heel rest into engagement with the heel end of the shoe, the relative amounts of movement thus imparted to the forepart grippers will be such that the gripper 105 which is located nearer to the toe end of the shoe, will always be positioned substantially midway between the other forepart gripper 106 and the rearmost toe gripper 104 on that side of the shoe. As will presently appear, the forepart grippers 105, 106 on each side of the shoe are drawn toewardly with the upper materials in response to lengthwise pulls imparted by toe grippers 102, 103 and 104. In some instances, especially on small shoes, the grippers 106, 106 may engage fingers 655. When this happens, the enlarged portion 704 in slot 702 permits the fingers 655 and bars 658 to move toewardly, as required.

Movements of the carriers 210 on each side of the shoe to position the ball lasting units relatively to the shoe being lasted also cause corresponding movements of the two shoe rest members 122 and 124 inasmuch as the members 218 on which these shoe rest members are pivotally supported are each secured to one of the gibs 216 associated with the carriers 210, see Figs. 25 and 26 wherein the shoe rest member 124, together with its support 218, is illustrated. Similarly, each of the insole holdowns 130, 133 is moved toewardly of the shoe through the action of the spring 234, see Fig. 25, wherein the insole holdown 133 is shown. When the heel rest 136 is retracted, at the conclusion of the lasting operation, it is possible that one or the other of these two holdowns may be held against movement by engagement with the bottom of the shoe and if such condition exists, the widened portion 704 of the slot 702 in arm 700 will provide sufficient lost motion to prevent damage to the parts.

Referring to Figs. 4 and 32 to 38, the toe gripper 100 is shown as provided, in addition to the usual inner and outer jaws 460, 462, with an intermediate jaw 750, this intermediate jaw being pivotally mounted on the same pivot pin as the outer movable jaw 460, see Figs. 32 and 34 wherein this pivot pin is identified by the reference character 752. The intermediate jaw has a relatively smooth operating face 754 on the side adjacent to the serrated operating face 466 of the fixed or inner jaw 462, and a serrated face 756 on the side adjacent to the smooth operating face 464 of the movable jaw 460. The weight of the intermediate jaw and the action of a spring, to be mentioned below, normally holds it in the position shown in Fig. 32, which position is such as to facilitate the insertion of the lasting margin of the upper materials of an ordinary shoe, which extend outwardly from the side of the last at an angle to the bottom of the shoe, into the open gripper jaws. With shoes of the mocassin type, however, the lasting margin tends to project straight downwardly substantially perpendicular to the bottom of the last. To facilitate the insertion of the lasting margin of uppers of this type, the intermediate jaw 750 may be swung in a clockwise direction and into engagement with the outer or movable jaw 460 by means of an operating lever 758. This lever is pivotally mounted on the outer jaw by means of a pin 760 and has a flat operative end 762 against which a cooperating flat surface 764, formed on an extension of the intermediate jaw, is held by the action of a spring 766 when the lever 758 is swung in a counterclockwise direction, in a manner which should be readily understood, see especially Fig. 33 wherein the aforementioned lever has been partially swung toward its operative position and Fig. 34 wherein the jaw

750 is shown in its other position. If desired, other of the forepart grippers, for example the toe grippers 102, 102, 103 and 103 may be provided with the above-described type of multiple gripper jaw arrangement.

After the forepart grippers have been operated to seize and to tension the upper materials around the toe end and forepart of the last and just before these grippers are opened to release the upper materials so that the lasting margin thereof may be wiped inwardly over and pressed against the bottom of the insole on the last by the forepart wipers 110, 110, the toe band 118 is moved into operative position for clamping the upper materials against the last and immediately after these grippers have been opened, the toe rest 134 is moved into operative engagement with the toe end of the shoe to support the shoe against the pressure applied by the wipers 110, see Figs. 33 and 34 of the drawings. Secured to the upper side of the portion 160 of the frame construction is an auxiliary housing 800, Figs. 1, 19, 20 and 21, which is formed on its upper portion with three guideways 802 in which there are mounted three slides 804, 806 and 808, Figs. 19 and 20. At its midpoint, the toe band 118 is secured to a lever 810 which is pivotally mounted on the forward (right hand) end of the slide 806, and yieldingly held in the elevated position shown by means of a compression spring 812, Fig. 21, while at its opposite sides the toe band is supported by two arms 814, 814, each pivotally mounted for swinging movement on the forward ends of the slides 804, 808, Fig. 19. Connected to the rearmost ends of the three aforementioned slides are three rods 816 each of which has a threaded end passing through a clearance hole 818 formed in an abutment bar 820. Interposed between the bar 820 and a thrust washer on each of the rods 816 associated with the two slides 804, 808 is a relatively strong compression spring 822, while interposed between a thrust washer on the rod 816 associated with the slide 806 is a somewhat lighter compression spring 824, these springs being held under compression by means of nuts 826 and locknuts 828 on the threaded ends of the rods 816.

The bar 820 is connected, at its opposite ends, to the upper ends of a pair of arms 830, 830 which are fast on a shaft 832 journaled on the frame part 160 and also fast on this shaft is a lever 834 having a downwardly extending arm 836 and an upwardly extending arm 838, Fig. 21. A coil spring 839 surrounding the shaft 832 tends to swing the arms 830, 830 in a counterclockwise direction, Fig. 21, and to the extent determined by the engagement of a roller 840 on the arm 836 with a plunger 842, formed integrally with a piston H, see Fig. 41 in which this piston is shown diagrammatically as fitted within a cylinder 844. As will be apparent when fluid under pressure is admitted through a conduit 846 into the cylinder 844, the piston H will be moved to the left, and in a direction to swing the arms 830, 830 in a clockwise direction thereby advancing the toe band 118 into engagement with the upper materials around the toe end of the last of a shoe in the machine. As this occurs, the mid portion of the toe band will first come into contact with the upper materials at the extreme toe end of the last whereupon the spring 824 will yield so that the toe band is, in effect, wrapped around the toe end and forepart of the shoe by the action of the arms 814, 814 and slides 804, 804. Continued movement of the piston H and arms 830, 830 to an extent determined by the engagement of an adjustable stop screw 848 with a suitable abutment, not shown, will compress the springs 822, 822 and 824 thereby yieldingly forcing the toe band into firm engagement with the upper materials around the toe end and forepart of the last.

The toe pad 134 is detachably mounted on the forward (right hand) end of a supporting member 860 which is slidably mounted in guideways 862 provided in a longitudinally extending portion 864 which is formed integrally with a generally U-shaped member 866 pivotally

mounted, by means of pins 868, 868 on the aforementioned housing 800, Figs. 19, 20 and 21. As is shown more clearly in Fig. 21, the forward end of the member 860 projects through a clearance opening 870 formed in an upstanding front web portion of the housing 800. The member 860 and toe pad 134 are held in the retracted positions in which they are shown in Fig. 21 by the engagement of adjustable stop screws 872, threaded onto the left-hand end of a rod 874, with an abutment plate 876 secured to the aforementioned slide 806. At its right-hand end this rod is connected to the member 860 by means of a pin 877. Pivotally mounted on two ears 878, carried by the member 860 and one of which appears in Fig. 21, is an L-shaped lever 880 having a downwardly turned operating end 882 and an upwardly projecting arm 884 which extends through a clearance slot 886 in the member 860 and into a groove 888 formed in the longitudinally extending portion 864 of the U-shaped member 866. Secured to the arm 884 of the lever 880 is a rod 890 which extends rearwardly and has a threaded end passing through a clearance hole in a plate 892 secured to the member 860. Surrounding this rod and interposed between the plate 892 and a thrust washer on this rod is a compression spring 894. The plate 892 carries a piston 896 which projects part way into a cylinder bore 898 formed on the top of the longitudinally extending portion 864 of the U-shaped member 866, and having a bleed port 900, Fig. 21. Carried by each of the downwardly extending opposite end portions of the U-shaped member 866 is a roller 902, Fig. 19, which is held yieldingly, by means of springs 903, 903, Fig. 20, against pistons I, one of which pistons is diagrammatically illustrated in Fig. 41 of the drawings and each of these pistons being slidable within a cylinder 906, see also Figs. 4 and 19.

As the slide 806 is moved to the right, Fig. 21, to bring the toe band 118 into its operative position in engagement with the upper materials around the toe end of the shoe being lasted, in the manner noted above, the abutment bar 876 will come into engagement with a coil spring 908 surrounding the rod 874 and through this spring the member 860 will be urged to the right against a dashpot action provided as the piston 896 enters the cylinder bore 898 and drives air out of this cylinder through the bleed port 900. Further movement of the member 860 and toe rest 134 which is carried thereby will be prevented when the piston 896 advances to the end of the bore 898. At an appropriate time in the operating cycle fluid under pressure will be admitted to the cylinders 906, 906 through conduits 910, 910, thereby operating the pistons I, I, to cause the U-shaped member 866 to be swung in a counterclockwise direction, Fig. 21, thus bringing the toe pad 134 into engagement with the toe end of the shoe, see Figs. 33 and 34. During this movement of the toe rest 134 into engagement with the shoe, the operating end 882 of the lever 880 will engage the toe band 118 and apply a yielding pressure thereagainst through the action of the spring 894.

Referring to Figs. 22 and 26, each of the two ball lasting units, which are of similar construction, has a wiper supporting arm 950 which is pivotally mounted, by means of a cross shaft 952 in two upstanding ears 954, 954 formed integrally with the carrier 210. Mounted on this arm is a hollow tube or sleeve 956, Fig. 3, on which there is slidably supported a movable cylinder block or hollow piston R, this cylinder block or piston also engaging a flat surface 960 formed on a forwardly extending portion 962 of the arm 950, Fig. 22. Also slidably mounted on the surface 960 of the arm 950, as shown in Fig. 26, is a wiper supporting member 964. Fastened to this supporting member is a ball wiper 114, and pivotally mounted thereon, by means including a shaft 966, is a second ball wiper 116, see Fig. 22. Secured to the shaft 966 is an arm 968 which extends beneath the arm portion 962 and carries a cam roller 970 which is received within

a cam track 972 formed in the lower side of the wiper supporting arm portion 962, Fig. 3. Adjustably connected to the wiper supporting member 964, by means including a rack and pinion and a spring locked hand knob 974, is a plunger 976 which bears against a compression spring 978 mounted in a bore in the movable cylinder block or piston R. Also connected to each of the wiper supporting members is a plunger 979 forming part of a valve member which is diagrammatically illustrated in Fig. 41 of the drawings and identified by the reference character V-38. As will presently appear, when the parts are in the positions in which they are shown in Figs. 3 and 41 of the drawings, a supply conduit 980 is connected to a conduit 982 and an exhaust line leading from the aforementioned valve is shut off by the plunger 979. However, when the plunger 979 is shifted to the left, Fig. 3, as a result of a yielding of the spring 978 in response to resistance to further movement of the wiper supporting member 964 by the aforementioned piston R, flow of operating fluid from the supply conduit 980 to the conduit 982 will be shut off and the conduit 982 will be connected to the exhaust line 984.

Connected to the hollow tube 956, mentioned above, is a conduit 986 through which, at an appropriate time in the operating cycle, as will presently appear, fluid under pressure is admitted to this tube for moving the movable cylinder block or piston R to the right (Fig. 41) for operating the wiper supporting member 964. For returning the wiper supporting member and the wipers carried thereby to the positions shown in Fig. 3, when the conduit 986 is connected to exhaust, a compression spring 988 is provided. During a final portion of the movement of the wiper supporting member by the piston R, the roller 970, which is associated with the wiper 116, rides into a curved portion of the cam groove 972 so that the wiper 116, shown on the right in Fig. 3 of the drawings, will be swung in a counterclockwise direction to fit behind an end portion of the wiper 114 which is shaped to receive the wiper 116 as shown in Fig. 3.

Connected to the portion 962 of the wiper supporting arm, by means of a stud 1000, is the upper end of a piston E, Figs. 26 and 41, this piston being slidable within a cylinder bore 1002 formed in the carrier 210, Fig. 26, and having a shoulder portion 1004 located within an enlarged part 1006 of the aforementioned bore. A coil spring 1008, bearing at its lower end against an adjusting plug 1010, tends to hold the piston E and the wiper supporting arm 962 in the elevated positions in which they are shown in Figs. 22 and 26 of the drawings, when a conduit 1012, which leads to the enlarged portion 1006 of the bore 1002, is connected to exhaust. As will presently appear, when the machine is being used, but before the initiation of an operating cycle, fluid under pressure is admitted to the conduits 1012, there being two of these, one for each ball wiping unit, so that each piston E is moved downwardly, Figs. 26 and 41, against the action of its spring 1008, thereby lowering the ball wipers from their operative positions. During the operating cycle, as will presently appear, the conduits 1012 are connected to exhaust so that the wiper supporting arms 962 are elevated by the springs 1008 to move the ball wipers upwardly into their operative positions as determined by the engagement of the shoe rest members 126, 128, each of which is carried by one of the arm portions 962, with the bottom of the shoe being lasteted, see Fig. 22.

Each of the ball grippers 112 comprises a pair of jaws 1030, 1032, Fig. 23, pivotally mounted, by means of a pin 1034 on a pair of arms 1036 formed integrally with a head member 1038, one only of these two arms appearing in Fig. 23. The aforementioned head member is mounted on the upper end of a tube 1040 and has a central bore 1042 through which extends a piston rod 1044 having secured to its upper end a wedge-shaped cam 1046. Associated with the gripper jaws 1030, 1032 are cam rollers 1048, 1048 which are adapted to be

engaged by the cam 1046 when it is moved upwardly, for closing the jaws against the action of a relatively light spring 1050. On the lower end of the rod 1044 there is a piston F which is slidable within the tube 1040 and a compression spring 1054 is adapted to hold the parts yieldingly in the position shown in Figs. 22 and 23. The lower end of the tube 1040 is closed by means of a plug-like member 1056 from which there projects a stem 1058 provided with a central bore 1060 and a ball-like enlargement 1062 by means of which it is connected to one end of an arm 1064. Connected to this stem is a conduit 982. As shown in Fig. 22, the upper end of the tube 1040 associated with each ball gripper is somewhat loosely guided by means of a loop-like spring 1066 mounted on a part of the carrier 210.

The arm 1064 is pivotally mounted, by means of a pin 1068 in the lower ends of two arms 1070, 1070 which extend downwardly from the carrier 210, Fig. 24, and has an upwardly turned end 1072. A coil spring 1074, Fig. 22, tends to swing the arm 1064 in a counterclockwise direction thereby elevating the gripper 112 to an extent determined by a stop pin 1076. This pin is carried by an arm 1078 fast on a shaft 1080 which carries a second arm 1084, Fig. 24. This shaft extends through a plate 1086 which is supported on the shaft 1080 and held against rotation, relatively to the carrier 210, by means of a screw 1087, Fig. 22. This plate is provided with an arcuate series of holes 1088 for receiving a spring plunger 1090, associated with the arm 1084, thereby to hold the arm 1084 in different angular positions and the gripper 112 in different heightwise positions. As is shown in Fig. 3 of the drawings, the upper edge of the plate 1086 is preferably provided with suitable indicia for facilitating the heightwise adjustment 35 of the ball gripper 112. Fitted with a cylindrical bore 1100 formed in the carrier block 210 is a piston G having a stem 1102 which projects downwardly through the carrier block and into a spherical recess 1104 in the arm 1064. When fluid under pressure is admitted 40 to the bore 1100, above the piston G, through a conduit 1106, see Fig. 41, the arm 1064 will be swung in a clockwise direction and the gripper 112 will be moved downwardly to exert a pull on the upper material seized thereby.

As will be explained below, at the beginning of each operating cycle, fluid under pressure is admitted to the spaces 1006 in the cylinder bores 1002, Fig. 26, forcing pistons E downwardly and swinging the wiper supporting arms 962 in a clockwise direction, Fig. 22, thereby lowering the wipers 114 and 116 of each ball lasting unit, and the shoe rest members 126, 128, associated respectively with these ball wiper units, to a location below their operating positions. Such downward movement of the wiper supporting arms 962 acting through a push 50 bar 1120, Fig. 22, also swings the arms 1064 in a clockwise direction to lower the grippers 112. The bar 1120 is connected at its lower end to the arm 1064 and has a slotted upper end which engages a pin 1122, Fig. 26. Slidably mounted on a guide member 1124 secured to the wiper supporting arm 962 is a carriage 1126 provided with a curved guide finger 1128. Pivotally mounted on a pin extending outwardly from the wiper supporting arm is a bell-crank lever 1129 having an upwardly extending arm provided with a forked end 1130 which 55 embraces a pin 1132 on the carriage 1126. Connected to the other arm 1134 of this bell-crank lever is a coil spring 1136. When the arm 962 is in its lowered position, at the beginning of each operating cycle, the arm 1134 of the aforementioned bell-crank lever will strike an abutment 1138 mounted on the carrier 210 thereby moving the carriage 1126 and the finger 1128 to the left, Fig. 22. Now, as the wiper supporting arm 962, together with the gripper 112, are permitted to rise to their operating positions, under the action of the springs 70 1008 and 1074, so that the shoe rest 128 (or 126) is

brought into engagement with the insole I of the shoe being lasted, the spring 1136 will swing the bell-crank lever in a clockwise direction and thus move the carriage 1126 and finger 1128 to the right thereby causing the finger 1128 to engage the upper materials and "steer" the lasting margin thereof into a position to be seized by the jaws 1030, 1032 of the gripper 112.

The forepart wipers 110, 110 are each secured to a wiper carrier 1150, mounted for arcuate swinging movement on a supporting plate 1152, and this supporting plate is, in turn, mounted for longitudinal sliding movement in a wiper housing 1154, Figs. 27 and 29. As is shown in Figs. 20 and 28, the wiper housing, which has a cover 1156, is provided with two downwardly extending webs 1158 by means of which it is slidably mounted on guideways 1160, formed in the aforementioned frame member 160, and held in place by means of rollers 1162. Connected to the wiper housing by means of a bracket 1164 and a piston rod 1166 is a piston K, Fig. 41, which is received within a bore 1172 formed in a cylinder block 1174, this block being mounted on the frame portion 160. As will presently appear, fluid under pressure may be admitted to, or exhausted from the bore 1172 through ports 1176, 1178 and conduits 1180, 1182 for effecting movement of the wiper housing toward and from its operating position. For checking movement of the housing in either direction, the piston K is provided with metering slots 1184, 1186 and the flow of operating fluid outwardly from the opposite ends of the cylinder bore 1172 is prevented, when one or the other of the ports 1176 or 1178 is closed by the piston K, by means of check valves 1188, 1190, in a manner which should be apparent.

Pivottally connected to each wiper carrier 1150, by means of a pin 1192, is one end of a link 1200 the other end of which is pivottally connected, by means of a pin 1194, to a crosshead 1202 formed integrally with a hollow head construction or piston M, Fig. 27. This piston is slidably mounted on a post 1206 which is carried by the housing 1154 and which has a head portion 1208 and two passages 1210, 1212 communicating, respectively, with spaces within the hollow piston M on the opposite sides of the head portion 1208. As is shown in Fig. 30, the hollow piston is provided with ribs 1214 which engage guideways 1216 formed in the housing 1154. Also pivottally connected to the crosshead 1202 by means of the pins 1194 are two double links 1224, 1224, Fig. 31, each provided with elongated slots 1226 through which one of two pins 1218 projects, these pins being carried by two levers 1220, pivottally mounted on the housing 1154 by a pin 1222, and located at the lower ends of these slots when the parts are in the positions in which they are shown in Fig. 27 of the drawings. The wiper supporting plate 1152 has two spaced-apart ears 1230, 1230 which are connected, respectively, by means of a pin 1232 to one of the levers 1220, and also connected to these levers are tension springs 1234, 1234. Mounted on the wiper supporting plate by means of pins 1236, 1236 is a spade-shaped auxiliary wiper 1238 having a stem 1240 and a crosspiece 1242.

When the machine is in use, but before the initiation of an operating cycle, fluid under pressure is admitted to the right-hand end of the bore 1172, Fig. 31, through conduit 1182, and also through a branch of this conduit to the passage 1212 in the post 1206. During the operating cycle, and near the latter portion thereof, the conduit 1182 is connected to exhaust and fluid under pressure is admitted to the left-hand end of the bore 1172 through conduit 1180, this fluid under pressure acting on the piston K and tending to move the wiper housing 1154 and parts carried thereby, including the wipers 110, 110, to operative position. Such movement of the wiper housing is, however, normally prevented by means of a detent lever 1250 having an arm 1252 the end of which is held in alinement with a stop pin 1254 carried by one of two

cam plates 1256, secured to the wiper housing, Figs. 20 and 21, by means of a spring 1258. This lever has an offset portion 1260 which is in alinement with a piston L slidable within a cylinder 1262 so that, when fluid under pressure is admitted to this cylinder, through a branch of the conduit 1180, see Fig. 41, the detent lever 1250 will first be swung away from the stop pin 1254, thereby releasing the wiper housing for movement, and then the wiper housing will be moved to operative position by the piston K.

As will presently appear, after the wiper housing has been moved to operative position in which the mid-portion of the open forepart wipers 110, 110 will have just commenced to wipe the lasting margin of the upper materials inwardly over the toe end of the shoe, fluid under pressure is admitted to the passage 1210 through a conduit 1270, thus causing the hollow piston M to be moved downwardly, Fig. 27, to the left Fig. 41. As this piston moves in this direction, the wiper carriers 1150 will be swung in directions to close the wipers 110, 110 through the action of links 1200, 1200, the springs 1234, 1234 now holding the levers 1220, 1220 in the positions shown, and the links 1224, 1224 moving downwardly as permitted by the slots 1226, 1226 therein. Before the wipers 110, 110 are fully closed and after the lasting margin of the upper materials has thus been wiped inwardly over the insole around the entire forepart of the shoe, the upper ends of the slots 1226, 1226 come into engagement with the pins 1218, 1218 thereby swinging the levers 1220, 1220 in directions to effect a lengthwise movement of the wiper supporting plate 1152 and a resulting advancement of the wiper carriers 1150 and wipers 110 as the wipers continue to close. In this way, the wipers 110 are first advanced in a fully opened relation until the mid-portion of these wipers has commenced to wipe the upper material inwardly over the insole at the toe end of the shoe, next the wipers are partially closed without any advancing movement until the upper ends of the slots 1226 engage pins 1218. Now these wipers are advanced and closed simultaneously to complete the forepart lasting operation.

Referring to Figs. 20 and 21, each of the cam plates 1256, referred to above, is provided with a slot 1280 having an upturned end 1282. Received within each of these slots is a roller 1284 which is carried by an arm 1286 on one of the previously mentioned levers 618. Thus, when the wiper housing 1154 is moved toward its operative position, in the manner which has just been explained, the levers 618 will each be rotated in a clockwise direction, Fig. 21, and as a result of such rotation of these levers, the plate 486, Fig. 4, will be moved downwardly to retract the forepart grippers out of the way of the forepart wipers if any of these grippers have not previously been retracted either by the action of gravity or otherwise.

The operation of the machine as a whole may be best explained in connection with a description of the fluid pressure operating system which is diagrammatically illustrated in Fig. 41 of the drawings with some of the more important elements thereof shown in other figures to be referred to below. As has been suggested above, the various operating elements of the herein illustrated machine are actuated by fluid pressure operated pistons under the control of a number of sequence valves, together with two treadle operated control valves provided for starting and terminating each operating cycle. Referring particularly to Fig. 41, a pump P, driven by a motor Mo, is arranged to receive operating fluid, such as oil, from a sump S and to deliver this fluid to a maximum pressure regulating valve V-26, this regulating valve being of conventional construction and adapted to be adjusted to vary the maximum pressure of the operating fluid, by means of a hand wheel 1300, see Figs. 2 and 35, and the pressure of the operating fluid thus regulated being indicated by means of a gage X. Normally, the operating fluid from this pump flows directly through a

first treadle operated control valve V-1 to a line *a*, this valve being diagrammatically illustrated and having a plunger, not shown, but adapted to be moved to the right in response to the depression of the treadle 152 (manual operation), and to the left by a fluid operated piston, not shown (hydraulic operation).

As is illustrated in more detail in Figs. 2 and 35, the treadle 152 has an upwardly extending arm 1302 adapted to engage a downwardly extending arm 1304 on an intermediate lever 1303 having one arm 1305 connected to a valve operating rod 1306. Inasmuch as the arms 1302 and 1304 are not mechanically connected together, the plunger of the valve V-1 will remain in the position to which it is moved in response to the depression of the treadle 152 after this treadle has been released and returned to its original position by means of a spring 1310, Fig. 35. Actually, a ball detent, not shown, associated with the plunger of the valve V-1, is provided for holding the plunger as well as the valve operating rod 1306 and the intermediate lever 1303 mentioned above in the positions to which they are moved by the treadle. The intermediate lever also has a third arm 1312 which supports the lower end of a push rod 1314, Fig. 2, which rod is guided at its upper end by means of an eye bolt 1316 threaded into the frame member 285 and normally held in the elevated position in which it is shown by means of a compression spring 1318 and the arm 1312. As will be apparent, after the treadle 152 has been depressed and released, the valve plunger of the valve V-1 may be returned to its original position by a downward movement of the rod 1314.

The pressure of the operating fluid in the line *a* is determined by a relief valve V-3, set for approximately 220 p.s.i., and this operating fluid flows through the line *a* and its various branches to the following operating pistons; to the forepart wiper carrier operating piston K, and to the forepart wiper operating piston M, through conduits 1182, thus holding the forepart wiper carrier 1154 and the forepart wipers 110 in retracted positions; and through a check valve V-5 and conduits 478 to the several forepart gripper elevating and positioning pistons B, thereby elevating the forepart grippers from the positions in which they are shown in Fig. 1 to heightwise positions corresponding to that indicated in Fig. 4. Connected to the conduit 478 is an accumulator Z which, of course, is charged with operating fluid as the operating fluid flows to the pistons B. Operating fluid from the line *a* also flows through a check valve V-7 and a so-called differential valve V-9 to the conduits 1012 leading to the pistons E associated with the ball wiper units, thereby maintaining the ball wipers, and through the action of the push rods 1120, Fig. 22, the ball grippers in retracted or lowered positions. As will be understood, excess oil is returned to the sump S through the relief valve V-3. Referring to Fig. 38, the differential valve V-9 has a plunger 1320 which is normally held, by means of a light spring 1322, in the position shown, in which position the line *a* is connected to the conduits 1012. As will presently appear, when fluid under pressure is admitted through a line *f* this plunger will be moved to and held in an elevated position in which the conduits 1012 are connected to an exhaust passage 1324 and flow through the line *a* to these conduits is shut off. As will presently appear, at a later point in the operating cycle of the machine, fluid under pressure is admitted to the valve V-9 through a line *m*, thus returning the plunger to the position in which it is shown in Fig. 38.

Upon the depression of the treadle 152, the plunger, not shown, of the valve V-1 is shifted to the right, Fig. 41, so as to permit fluid under pressure from the pump P to flow directly through this valve and, through the second treadle valve V-2, into a line *b* in which the pressure of the fluid is limited by a relief valve V-4 set for about 360 p.s.i. Fluid under pressure flows from the line *b* and through a check valve V-6 into the aforemen-

tioned line *a*, the increased pressure of the operating fluid now in the line *a* and acting on the pistons B being sufficient to cause the forepart grippers to be swung inwardly, against the action of springs 424, Fig. 14, and into engagement with the sides of the last of the shoe in the machine. Operating fluid at this increased pressure also flows to the aforementioned pistons E for maintaining the ball wiper units in their retracted positions. One branch of the line *b* in which there is a restriction R-32 10 is connected to the conduit 310 which leads to the heel rest operating piston A in cylinder 304, Fig. 12, so that the operating fluid causes the heel rest 136 to move into engagement with the heel end of the shoe in the machine and to urge the shoe forwardly until its toe end comes 15 into contact with the toe gage 140. Another branch of the line *b* leads to a cylinder 1330 in which there is a piston T, Fig. 36, the function of which will presently be explained.

The treadle 154 has an upwardly extending arm 1332 20 adapted to engage a downwardly extending arm 1334 on a lever 1335 which has an upwardly extending arm 1336 connected to a valve operating rod 1338, Figs. 2 and 35. An offset portion 1339 on the arm 1336 extends in front of an offset portion 1340 on the arm 1305, previously 25 mentioned. Thus, when the treadle 154 is depressed against the action of a spring 1342, the rod 1338 will be moved rearwardly, i.e., upwardly in Fig. 35, thereby shifting the plunger (not shown) of the second treadle valve V-2, diagrammatically illustrated in Fig. 41, to the 30 right so as to connect the line *b* to exhaust. In order to prevent depression of the treadle 154 prior to the actuation of valve V-1 in response to depression of treadle 152, a stop 1344 is pivotally mounted on the treadle 154, Fig. 2, and extending between this stop and a third arm 1346 35 on lever 1303 is a link 1348. When valve V-1 is actuated, the stop 1344 is swung outwardly beyond the lower part of the frame 150 thereby freeing treadle 154 for depression by the operator. Return flow from the line *a*, and conduits 1012 and 478 is prevented by check valves 40 V-5 and V-6, while the plunger 1350 of a valve V-10A, Fig. 39 is held in an elevated position by a spring 1352 so as to shut off the flow from the line *a* to an exhaust passage 1354 in which there is a spring-loaded check valve V-36, Fig. 41. Any leakage which may occur 45 around the pistons B, or E, E will be immediately made up by fluid under pressure from the accumulator Z. Operating fluid from the pump P now flows through the valve V-2 into a line *c*. A branch of this line leads to a valve V-10C, Fig. 40, having a plunger 1360 which is 50 held in an elevated position, by a spring 1362, so as to permit flow of operating fluid from this branch of the line *c* to the conduit 454, thereby causing the forepart grippers to be closed to seize the lasting margin of the 55 upper materials of the shoe being lasted. Another branch of the line *c* leads to a chamber in the valve V-10A, above the plunger 1350 so that this plunger is now forced downwardly, against the action of the spring 1352, thereby connecting a part of the line *a* to exhaust through the 60 spring-loaded check valve V-36. The resistance set up by this check valve to the exhausting of fluid from the line *a* is sufficient to hold the forepart pincers in their elevated positions against the action of gravity. The check valve V-7 now prevents the exhausting of operating fluid from conduit 1012 and pistons E through valve 65 V-9 and line *a*.

Another branch of the conduit *c* leads to the first sequence valve V-12 which opens at a pressure of approximately 350 p.s.i. into a line *d*. Inasmuch as each of the 70 sequence valves provided in the herein illustrated machine are of similar construction, a description of the valve V-12 which is the first to be mentioned will be, it is believed, sufficient for all. As shown in Fig. 37, this valve has a ball 1370 which is adapted to be lifted off of its seat against the resistance of a spring 1372 to connect

the line *c* to the line *d*. Free return flow through this valve from line *d* to line *c* is permitted by a check valve 1374. Preferably, and as illustrated herein, the several sequence valves are of a novel and improved construction which is disclosed in a copending application Serial No. 600,591, filed in my name on July 27, 1956. As shown in Fig. 1 of the drawings, the several sequence valves are arranged in a row on a combined supporting bar and manifold 1376, Fig. 37, on which there may be conveniently mounted a drain pipe 1378. The line *d* is in communication with the conduits 522, 524 and 526 which lead to the several forepart gripper operating pistons D in a manner which will now be explained. As will be recalled, the conduit 522 leads to a manifold passage 520, see Fig. 10, which is connected to the cylinder bores 508 above the pistons D associated with the end gripper 100 and with the toe grippers 102, 102, 103 and 103; the conduit 524 has two branches connected respectively to the two cylinder bores 508 above pistons D associated with the other two toe grippers 104, 104; while the conduit 526 also has two branches connected, respectively, to manifold passages 525 leading to the cylinder bores 508 above the pistons D which are associated with the forepart grippers 105, 105, 106 and 106.

As shown in Fig. 41, the line *d* is connected directly to the conduit 522, while as illustrated in Fig. 4 the line *d* is also connected to an inlet port 1380 of an equalizing and timing valve V-13, shown also in Fig. 9. This valve comprises a cylindrical block 1381 having a central bore 1382 in which there is a valve plunger 1384 and two other smaller bores 1386, 1386 spaced 180° apart and overlapping the central bore. Radial ports 1390 connect these smaller bores with the conduits 524, 524, as shown in Fig. 9, and opening into these radial ports are vertical bores 1392 which open, at their lower ends into other radial ports 1394 leading to the central bore 1382. The conduits 525, 526 are connected to the central bore 1382 by means of other radial ports 1391 and vertical passages 1393 terminating in radial ports, not shown but corresponding to ports 1394. The valve plunger 1384 has cross passages 1396 which are in communication with a circumferential groove 1398. Fitted within each of the bores 1386 is a plunger 1400 having a stem 1402 and interposed between these pistons and closure plugs 1404 are compression springs 1406. The plunger 1384 is provided with return valve 1405 to permit exhausting of operating fluid from conduits 524, 524, 526, 526 when inlet port 1380 and line *d* are connected to exhaust.

When operating fluid is admitted to the line *d*, in the manner just explained above, the end gripper 100 and toe grippers 102, 102, 103 and 103 will first be moved downwardly by their pistons D so as to apply a tensioning pull to the upper materials seized thereby. Next, as the pressure of the operating fluid elevates the valve plunger 1384, against the resistance of the springs 1406, operating fluid within the bores 1386, 1386 and the conduits 524, 524 will transmit the movement of the pistons 1400 by the valve plunger 1384 to the pistons D which are associated with the two rearmost toe grippers 104, 104, so that these grippers are moved downwardly equal distances as they apply a tensioning pull to the upper materials seized thereby. Now, when the valve plunger 1384 has been elevated to a position in which its lower end is above the radial ports 1394, operating fluid will be admitted to the vertical passages or bores 1393 and hence to the conduits 526 thereby causing the forepart grippers 105, 105, 106 and 106 to be moved downwardly to apply their tensioning pull on the upper materials seized thereby. In this manner, the several forepart grippers are operated in a definite predetermined sequence so that the end gripper 100 and toe grippers 102, 102, 103 and 103 operate first, this action being followed by the operation of the two other toe grippers 104, 104, with the equalizing action mentioned above. After these grippers, which it will be recalled are also caused to move in direc-

tions extending lengthwise of the shoe in response to their downward movements, have been operated, the forepart grippers 105, 105, 106 and 106, which are free to move lengthwise of the shoe with the upper materials as they are drawn toward the toe end of the last by the lengthwise movements of the other forepart grippers, are operated to apply their tensioning pull on the upper materials. As will be recalled, the extent of movement of each of the forepart grippers is determined by the engagement of the rod 512, on its associated piston D with a stop screw 530, Fig. 3.

When all of the forepart grippers have thus been operated, the pressure of the fluid in the lines *d* builds up to a value where sequence valve V-14, set for a pressure of about 400 p.s.i., opens to admit operating fluid to a line *e* which leads to a cycle interrupting valve V-15. Referring to Fig. 36, this valve has a plunger 1410 for controlling the flow of operating fluid from the line *e* to a line *f*, this plunger having an upwardly extending stem 1412 which projects outwardly through a bushing 1414. This stem is connected to one arm of the previously mentioned hand lever 156 by means of a link 1418 and bell-crank lever 1420, the lever 156 being pivotally mounted, by means of a pin 1422, on a portion of the frame construction 160 and having one of its arms extending well above the frame, see also Figs. 1 and 3. Also pivotally mounted, by means of a pin 1424, on the frame at the other side of the last mentioned instrumentalities is the previously mentioned hand lever 158, and connected to this lever is one end 30 of a link 1426. The other end of this link is connected to one arm of an L-shaped lever 1428 the other arm of which has a rounded end 1430 adapted to be received within a recess 1432 formed in the lever 156. When operating fluid was admitted to the cylinder 1330 behind the piston T, during an earlier stage in the operating cycle of the machine, the lever 158 was swung in a clockwise direction and to the extent determined by a stop pin 1434. Such movement of this lever, through the action of the link 1426 and the L-shaped lever 1428 with its rounded end 1430, swung the lever 156 in a counterclockwise direction to the extent determined by a stop screw 1436, thereby lifting the valve plunger 1410 to the position shown and in which position the line *e* is connected to exhaust and shut off from the line *f*. In this way, the cycle is automatically interrupted at this point and, in order for the operator to restart the cycle he must first swing the lever 158 in a counterclockwise direction, against the resistance of the piston T, which resistance is, of course, now very slight inasmuch as the line *b* has previously been connected to exhaust through the valve V-2, and then swing the lever 156, now released by movement of the end 1430 of the lever 1428 into alignment with the recess 1432, in a clockwise direction thereby moving the valve plunger 1410 downwardly to a position, determined by a stop screw 1438, in which the line *e* is disconnected from exhaust and is connected to the line *f*.

Operating fluid thus admitted to the line *f*, which has several branches, acts on the lower portion of the valve plunger 1320 of the differential valve V-9, Fig. 38, and by elevating this plunger against the resistance of the spring 1322 connects the conduits 1012 and cylinders 1002 to exhaust thereby releasing pistons E, E and permitting the ball wiper units to be moved upwardly to their operating positions by means of the springs 1008, Figs. 22 and 26. As the ball wiper units move to their operating positions, the ball grippers also are elevated and the last margin of the upper materials at the ball line is steered into the open jaws 1030, 1032 of the ball grippers by the action of the fingers 1128, 1128, see Fig. 22. Also, the operating fluid in a branch of the line *f* acts on a dump valve V-16 to move its plunger, diagrammatically illustrated in Fig. 41, to the closed position in which it is shown against the resistance of a spring 1440. Still another branch of the line *f* leads to a sequence valve V-27 which is set to open when the pressure of the fluid in the

line *f* reaches 500 p.s.i., thus admitting operating fluid to a line *g* which is connected to the conduits 980 leading to the previously mentioned valves V-38 and through these valves, which are at this time open, to the conduits 982 leading to the ball gripper closing cylinders formed by the tubes 1040, and causing the jaws 1030, 1032 of these grippers to be closed by the pistons C, C.

Upon the closing of these jaws on the upper materials, pressure of the operating fluid in the line *g* builds up to a value sufficient to open sequence valve V-18 set for 510 p.s.i., thereby admitting operating fluid to a line *h* and to a line *l*. The line *h* is directly connected to the conduit 846 which leads, through a check valve V-39, to the cylinder 844 in which the toe band operating piston H is located so that this piston is actuated to apply the toe band 118 to the toe end of the shoe, see Figs. 33 and 34. The line *h* is connected through a pressure reducing valve V-19 to the conduit 264 which leads to the toe gage operating piston N and to the conduits 1106 which lead to the cylinders 1100 in which the ball gripper pull pistons G are located, Fig. 22, so that the ball grippers are operated to exert their tensioning pull on the upper materials with a force which may be varied by changing the setting of the valve V-19. As illustrated in Fig. 2, this valve, which is of a well-known commercial type, is preferably arranged to be adjusted by means of a hand wheel 1442 and a pressure gage Y is provided for indicating to the operator the magnitude of the force being applied by the ball grippers. As shown in Fig. 41, there is a restriction R-33 in the conduit 264 for controlling the flow of operating fluid into the cylinder 256 so as to slow down and regulate the movement of the piston N as it withdraws the toe gage 140 to the retracted position in which it is shown in Figs. 33 and 34. The line *l* leads to the valve V-10C, Fig. 40, and as operating fluid is admitted to the space above the plunger 1360 this plunger is forced downwardly, against the action of the spring 1362, thereby shutting off the flow of operating fluid from the line *c* to the conduit 454 and connecting this conduit to an exhaust passage 1444. The forepart grippers are now opened to release the lasting margin of the tensioned upper materials, which materials are, of course, snugly held against loosening by the action of the toe band 118. As they release their grip on the upper materials, the forepart grippers are free to drop by gravity to their lowered retracted positions.

As the pressure of the operating fluid builds up in the lines *h* and *l* to a value sufficient to open a sequence valve V-20 set for 525 p.s.i., this valve opens and operating fluid is admitted to a line *m*. The previously mentioned conduit 604 is connected to this line so that the pistons B which are associated with the forepart grippers 106, 106 are now forced downwardly, Fig. 17. Inasmuch as the rods 476 connected to the pistons B are secured to these grippers by pins 592, 594, these grippers are likewise moved downwardly and, because of the action of the abutments 596, 596, Fig. 16, carry with them the adjacent forepart grippers 105, 105. The conduits 910 are also connected to the line *m* and therefore the pistons I, I are actuated to swing the toe pad 134 downwardly into engagement with the toe end of the shoe, Fig. 33, such movement of the toe rest also causing the operating end 882 of the lever 880 to engage the toe band. The conduit 986 is also connected to the line *m* through a retarding valve V-29 which opens to admit operating fluid to the conduits 986 connected to the hollow tubes 956, see Fig. 3.

The ball wiper actuating pistons R, R are now actuated to effect inward movement of the ball wiper carriers 964 together with the ball wipers 114, 116, on each side of the shoe, through the action of springs 978. When these wipers engage the upper materials, still being held under tension by the ball grippers 112, 112, the resistance to inward movement of these wipers increases and the springs 978 yield. As a result of this yielding action between the pistons R and the wiper carriers 964, the

plungers 978, Fig. 3, of the valves V-38 are moved to positions in which the conduits 982 are shut off from the conduit 980 and instead are connected to the exhaust conduits 984. Thus the ball grippers now open and release the upper materials thereby permitting continued inward movements of the ball wiper carriers and ball wipers. The line *m* is also connected to the valve V-9, Fig. 38, and as operating fluid is admitted to the space above its plunger 1320, this plunger is forced downwardly to shut off the conduit 1012 from exhaust and to connect this conduit again to the line *a*. A branch of the line *m* also leads to the previously mentioned exhaust valve V-16 which, of course, at this time is closed.

Soon the pressure of the operating fluid in the line *m* builds up and opens a sequence valve V-21, set for 550 p.s.i., thereby admitting operating fluid into a line *n* which leads through check valves V-22 and V-8 and differential valve V-9 to the conduits 1012 thereby actuating the pistons E, E to withdraw the ball wiper units and ball grippers to their retracted and inoperative positions. The conduit 1180 is connected to the line *n* so that piston L is actuated to unlock the wiper head 1154, while piston K is actuated to move the wiper head forwardly to its operative position. A branch of the line *n* goes to the closed dump valve V-16. When the wiper head reaches its operative position, pressure of the operating fluid in the line *n* builds up and opens sequence valve V-23 thereby admitting operating fluid into a line *o*. Connected to one branch of this line is the conduit 1270 so that operating fluid now actuates the piston M to advance and to close the forepart wipers 110.

Another branch of the line *o* leads to a sequence valve V-24 which opens when pressure in the line *o* reaches 700 p.s.i. and admits operating fluid to a line *p* leading to a piston, not shown, associated with the treadle valve V-1. As this piston is acted upon by the operating fluid in line *p* the valve V-1 is returned to its original position, shown in Fig. 41, and because of the mechanical interlock provided by the offset portions 1339 and 1340, Fig. 35, treadle valve V-2 is likewise returned to its original position. The fluid pressure system is now opened to exhaust and dump valve V-16 is returned to open position by spring 1440. Operating fluid at idling pressure (valve V-3) now returns the pistons M, K and B to their initial positions, pistons I, H, G, L and N are returned by means of springs, while piston A is returned by the action of gravity. As the forepart grippers are elevated by operating fluid under idling pressure acting on the several pistons B, the pistons D will be picked up and returned mechanically by the action of the shoulders 518 and heads 514, Fig. 17. The operating plunger of the valve V-1 is held in the position to which it is moved by the treadle 152 by means of a mechanical detent, not shown, and this plunger is returned to its original position by means of operating fluid in the line *p* acting on a piston, not shown. In order to permit movement of this plunger and piston when the valve is again treadled, a check valve V-25, opening into the system, is provided, see Fig. 41.

Briefly summarizing the operation of the machine, with particular reference to the sequence of operations and the actions of the various operating elements, the operator places a shoe to be lasted, herein identified generally by the reference character Sh, Fig. 3, and shown as comprising an upper U assembled on a last La, together with an insole In, Figs. 22, 33, 34 and 35, in the machine with the bottom of its forepart supported on the several shoe rest members 120, 122 and 124, Fig. 3, and depresses the treadle 152, Figs. 2 and 35. The forepart grippers 102, 102, 103, 103, 104, 104, 105, 105, 106 and 106 are now swung inwardly against the last around the forepart of the shoe and the heel rest 136 is moved into engagement with the heel end of the shoe thereby urging the toe end of the last against the toe gage 140, Fig. 32. As a result of the pressure exerted against the sensing

finger 330, Figs. 3 and 12, the heel rest is now mechanically locked against retrograde movement and the shoe is held in place in the machine. Next, the operator inserts the lasting margin of the upper materials U into the open jaws of the several forepart grippers to the extent permitted by the gage plates 468, Fig. 14, and having thus arranged the upper, he depresses the treadle 154. The forepart grippers are now closed on the upper materials and are operated in a predetermined sequence to exert their tensioning pulls on the upper materials. As explained in detail above, certain of these grippers are caused to move in directions to exert a lengthwise pull on the upper materials and the components of lengthwise movements of these grippers are proportional to the distance the gripper is spaced from the toe end of the shoe. During this graded lengthwise pulling of the upper materials by certain of the forepart grippers, the other forepart grippers, i.e., those located most remotely from the toe end of the shoe, are free to move along with the upper materials prior to their operation to exert tensioning pulls thereon. In this way the upper materials are pulled over and shaped to the last with a combined heightwise and lengthwise pull.

The operating cycle is now interrupted automatically, thus giving the operator an opportunity to inspect the shoe with the upper materials held under tension. If for any reason the operator desires to do so, he may return the various operating elements to their initial positions by pushing downwardly on the rod 1314, Fig. 2. Otherwise, he may restart the operating cycle of the machine by swinging his two hands apart and striking the two levers 156, 158, Fig. 36, thereby opening the cycle interrupting valve V-15. As a matter of fact, the operator may swing his hands outwardly immediately after the upper materials have been seized by the forepart grippers in response to the depression of the treadle 154, thus, in effect, eliminating the interruption of the operating cycle. In either case, however, the operator must take both of his hands off of the shoe being lasted and move them outwardly away from each other to positions out of danger of possible injury by the wipers of the machine before the operating cycle can be resumed.

After the operating cycle has been resumed, the ball wipers 114, 116 and ball gripper 112 on each side of the machine are elevated to their operating positions as determined by the engagement of the shoe rests 126, 128 with the bottom of the shoe, see Fig. 22, whereupon the ball grippers 112, 112 close on the lasting margin of the upper materials at the ball portion of the shoe, which lasting margin is "steered" into position to be seized by these grippers as the result of the action of the fingers 1128, and these grippers are operated to exert their tensioning pulls on the upper materials. Now, the toe gage 140 is retracted and the toe band 118 is moved into operative position for clamping the upper against the last around the forepart of the shoe, Fig. 33. With the tensioned upper materials thus held against loosening, the forepart grippers are opened to release their grip on the lasting margin and then are free to fall by gravity to out-of-the-way positions. Next, the toe pad 134 is brought into engagement with the toe end of the shoe, Figs. 33 and 34, preparatory to the operation of the forepart wipers 110, 110 and ball wipers 114, 116. Also, the forepart grippers 105, 105, 106 and 106 are forcibly retracted, if they have not already dropped to out-of-the-way positions under the influence of gravity, by operating fluid under pressure admitted to the space above the two pistons B, B associated with forepart grippers 106, 106, see Fig. 17.

Now the ball wipers 114, 116 are operated to wipe the lasting margin of the upper materials inwardly over the bottom of the shoe in the vicinity of the ball line, and as these wipers engage the upper materials at the opposite sides of the shoe, still held under tension by the ball grippers, the resistance to further movements of

these wipers causes a yield between these wipers and their operating pistons which actuates a valve to effect opening of the ball grippers. As these grippers thus release the upper materials and move downwardly out of the way, 5 the ball wipers complete their inward wiping actions. As soon as the ball wipers have thus wiped the upper materials inwardly over the bottom of the shoe at the opposite sides of the shoe in the vicinity of the ball line, the ball wipers and with them the ball grippers are retracted to their inoperative positions and immediately 10 thereafter the forepart wiper head 1154 is unlocked and advanced to operative position. During this advance of the forepart wiper head, the plate 482, Fig. 4, is mechanically moved downwardly so as to retract any of the forepart grippers which may not have already dropped by gravity or otherwise been retracted to out-of-the-way positions. Finally, the forepart wipers 110, 110 are advanced 15 and closed to complete the lasting operation by wiping the lasting margin of the upper materials inwardly over the bottom of the shoe around its entire forepart, whereupon the treadle operated valves are automatically returned to their initial positions and the fluid pressure system of the machine restored to idling condition. The various operating elements are now returned to their initial positions by fluid pressure, gravity or springs, as the case may be, and the completely pulled over, toe and forepart lasted shoe is removed from the machine.

Having thus described my invention, what I claim as new and desire to secure by Letters Patent of the United States is:

1. In a machine for shaping uppers over lasts, means for supporting a last in position for the shaping of an upper thereover, a plurality of grippers mounted for movement heightwise and lengthwise of the last to pull the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, means for moving said grippers in directions extending heightwise of the last, and cam means for causing certain of said grippers also to move in directions extending lengthwise of the last to pull the upper over the last with a force exerted toward the toe end thereof in response to their movements heightwise of the last to pull the upper around the last.
2. In a machine for shaping uppers over lasts, means for supporting a last in position for the shaping of an upper thereover, a plurality of grippers mounted for movement heightwise and lengthwise of the last to pull the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, fluid pressure operated means for moving said grippers in directions extending heightwise of the last, and cam means for causing certain of said grippers also to move in directions extending lengthwise of the last to pull the upper over the last with a force exerted toward the toe end thereof in response to their movements heightwise of the last to pull the upper around the last.
3. In a machine for shaping uppers over lasts, means for supporting a last in position for the shaping of an upper thereover, a plurality of grippers mounted for movement heightwise and lengthwise of the last to pull the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, means for moving said grippers in directions extending heightwise of the last, and cam means for causing certain of said grippers also to move in directions extending lengthwise of the last to pull the upper over the last with a force exerted toward the toe end thereof in response to their movements heightwise of the last to pull the upper around the last.

4. In a machine for shaping uppers over lasts, means for supporting a last in position for the shaping of an upper thereover, a plurality of grippers mounted for movement heightwise and lengthwise of the last to pull the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, means for moving said grippers in directions extending heightwise of the last, and cam means for causing certain of said grippers also to move in directions extending lengthwise of the last to pull the upper over the last with a force exerted toward the toe end thereof in response to their movements heightwise of the last to pull the upper around the last.
5. In a machine for shaping uppers over lasts, means for supporting a last in position for the shaping of an upper thereover, a plurality of grippers mounted for movement heightwise and lengthwise of the last to pull the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, means for moving said grippers in directions extending heightwise of the last, and cam means for causing certain of said grippers also to move in directions extending lengthwise of the last to pull the upper over the last with a force exerted toward the toe end thereof in response to their movements heightwise of the last to pull the upper around the last.

direction extending lengthwise of the last toward its toe end and proportioned in accordance with the location of the gripper relatively to the toe end of the last.

12. In a machine for shaping uppers over lasts, means for supporting a last in position for the shaping of an upper thereover, a plurality of grippers mounted for movements heightwise and lengthwise of the last for pulling the upper in different locations around the toe end of the last and including an end gripper for pulling the upper at the extreme toe end of the last, and a plurality of toe grippers for pulling the upper, respectively, at each of the opposite sides of the toe end thereof, fluid pressure operated means for moving all of said grippers in directions extending heightwise of the last, and cam means for effecting a predetermined graded movement of each of said toe grippers in a direction extending lengthwise of the last toward its toe end and proportioned in accordance with the location of the gripper relatively to the toe end of the last.

13. In a machine for shaping uppers over lasts, means for supporting a last in position for the shaping of an upper thereover, a plurality of grippers mounted for movements heightwise and lengthwise of the last for pulling the upper in different locations around the toe end of the last and including an end gripper for pulling the upper at the extreme toe end of the last, and a plurality of toe grippers for pulling the upper, respectively, at each of the opposite sides of the toe end thereof, means for moving all of said grippers in directions extending heightwise of the last, and cam means operable in response to the heightwise movement of the grippers by said gripper moving means for effecting a predetermined graded movement of each of said toe grippers in a direction extending lengthwise of the last toward its toe end and proportioned in accordance with the location of the gripper relatively to the toe end of the last.

14. In a machine for shaping uppers over lasts, means for supporting a last in position for the shaping of an upper thereover, a plurality of grippers mounted for movements heightwise and lengthwise of the last for pulling the upper in different locations around the toe end of the last and including an end gripper for pulling the upper at the extreme toe end of the last, and a plurality of toe grippers for pulling the upper, respectively, at each of the opposite sides of the toe end thereof, fluid pressure operated means for moving all of said grippers in directions extending heightwise of the last, and cam means operable in response to the heightwise movement of the grippers by said gripper moving means for effecting a predetermined graded movement of each of said toe grippers in a direction extending lengthwise of the last toward its toe end and proportioned in accordance with the location of the gripper relatively to the toe of the last.

15. In a machine for shaping uppers over lasts, means for supporting a last in position for the shaping of an upper thereover, a plurality of grippers for pulling the upper in different locations around the toe end and forepart of the last including an end gripper for pulling the upper at the extreme toe end of the last, toe grippers for pulling the upper at the opposite sides of the toe end of the last, and a plurality of forepart grippers for pulling the upper, respectively, at each of the opposite sides of the forepart of the last between the toe end and ball portions of the last, a stop means for engaging and locating the toe end of each last placed on the supporting means in the same position relatively to said grippers, an abutment member mounted for movement toward said stop and into engagement with the upper at the heel end of the last, and means movable in directions extending lengthwise of the last in response to movement of said abutment member for positioning said forepart grippers lengthwise of the last in accordance with the size of the last as determined by the movement of said abutment member.

16. In a machine for shaping uppers over lasts, means for supporting a last in position for the shaping of an upper thereover, a plurality of grippers for pulling the upper in different locations around the toe end and forepart of the last including an end gripper for pulling the upper at the extreme toe end of the last, toe grippers for pulling the upper at the opposite sides of the toe end of the last, and a plurality of forepart grippers for pulling the upper, respectively, at each of the opposite sides of the forepart of the last between the toe end and ball portion of the last, a stop means for engaging and locating the toe end of each last placed on the supporting means in the same position relatively to said grippers, an abutment member mounted for movement toward said stop and into engagement with the upper at the heel end of the last, guide means associated with each of said forepart grippers, and means for effecting movement of said guide means in directions extending lengthwise of the last in response to movement of said abutment member for positioning said forepart grippers lengthwise of the last in accordance with the size of the last as determined by the movement of said abutment member.

17. In a machine for shaping uppers over lasts, means for supporting a last in position for the shaping of an upper thereover, a plurality of grippers for pulling the upper in different locations around the toe end and forepart of the last including an end gripper for pulling the upper at the extreme toe end of the last, toe grippers for pulling the upper at the opposite sides of the toe end of the last, and a pair of forepart grippers for pulling the upper, respectively, at each of the opposite sides of the forepart of the last between the toe end and ball portion of the last, a stop means for engaging and locating the toe end of each last placed on the supporting means in the same position relatively to said grippers, an abutment member mounted for movement toward said stop and into engagement with the upper at the heel end of the last, and means operable in response to movement of said abutment member for effecting movements of said forepart grippers in directions extending lengthwise of the last toward the toe end thereof in accordance with the size of the last as determined by the movement of said abutment member, said movements being so proportioned that the forepart gripper nearest to the toe portion of the last is always positioned midway between the other forepart gripper and the rearmost toe gripper.

18. In a machine for shaping uppers over lasts, means for supporting a last in position for the shaping of an upper thereover, a plurality of grippers for pulling the upper in different locations around the toe end and forepart of the last including an end gripper for pulling the upper at the extreme toe end of the last, toe grippers for pulling the upper at the opposite sides of the toe end of the last, and a pair of forepart grippers for pulling the upper, respectively, at each of the opposite sides of the forepart of the last, between the toe end and ball portion of the last, a stop means for engaging and locating the toe end of each last placed on the supporting means in the same position relatively to said grippers, an abutment member mounted for movement toward said stop and into engagement with the upper at the heel end of the last, a guide means associated with each of said forepart grippers, and means operable in response to movement of said abutment member for effecting movements of said guide means for positioning said forepart grippers in directions extending lengthwise of the last toward the toe end thereof in accordance with the size of the last as determined by the movement of said abutment member, said movements of the guide means being so proportioned that the forepart gripper nearest to the toe portion of the last is always positioned midway between the other forepart gripper and the rearmost toe gripper.

19. In a machine for shaping uppers over lasts, means for supporting a last in position for the shaping of an upper thereover, a plurality of fluid pressure operated

grippers for pulling the upper in different locations around an end portion of the last, a pair of fluid pressure operated wipers for wiping the lasting margin of the upper inwardly over an insole on said end portion of the last, a source of fluid under pressure, control valve means for initiating an operating cycle of the machine, a plurality of sequence valves for controlling the operation of said grippers and said wipers in predetermined sequence in the course of an automatic operating cycle, a cycle interrupting valve associated with said sequence valves and adapted to be set for discontinuing the flow of fluid under pressure to certain of said sequence valves for interrupting the operating cycle, and operator controlled means for actuating said cycle interrupting valve to reestablish flow of fluid under pressure to said sequence valves thereby to continue said automatic operating cycle.

20. In a machine for shaping uppers over lasts, means for supporting a last in position for the shaping of an upper thereover, a plurality of fluid pressure operated means for pulling the upper in different locations around an end portion of the last, and a pair of fluid pressure operated wipers for wiping the lasting margin of the upper inwardly over an insole on said end portion of the last, a source of fluid under pressure, control valve means for initiating an operating cycle of the machine, a plurality of sequence valves for controlling the operation of said grippers and wipers in predetermined sequence in the course of an automatic operating cycle, a cycle interrupting valve associated with said sequence valves adapted to be set in response to operation of said control valve means for discontinuing the flow of fluid under pressure to certain of said sequence valves for interrupting the operating cycle prior to the operation of said wipers, and operator controlled means for actuating said cycle interrupting valve to reestablish flow of fluid under pressure to said sequence valves thereby to continue said automatic operating cycle.

21. In a machine for shaping uppers over lasts, means for supporting a last in position for the shaping of an upper thereover, a plurality of fluid pressure operated means for pulling the upper in different locations around an end portion of the last, and a pair of fluid pressure operated wipers for wiping the lasting margin of the upper inwardly over an insole on said end portion of the last, a source of fluid under pressure, control valve means for initiating an operating cycle of the machine, a plurality of sequence valves for controlling the operation of said grippers and wipers in predetermined sequence in the course of an automatic operating cycle, a cycle interrupting valve associated with said sequence valves and adapted to be set for discontinuing the flow of fluid under pressure to certain of said sequence valves for interrupting the operating cycle, and operator controlled means adapted to be engaged by the hands of the operator for actuating said cycle interrupting valve to reestablish flow of fluid under pressure to said sequence valves thereby to continue said automatic operating cycle.

22. In a machine for shaping uppers over lasts, means for supporting a last in position for the shaping of an upper thereover, a plurality of fluid pressure operated means for pulling the upper in different locations around an end portion of the last, and a pair of fluid pressure operated wipers for wiping the lasting margin of the upper inwardly over an insole on said end portion of the last, a source of fluid under pressure, control valve means for initiating an operating cycle of the machine, a plurality of sequence valves for controlling the operation of said grippers and wipers in predetermined sequence in the course of an automatic operating cycle, a cycle interrupting valve associated with said sequence valves and adapted to be set for discontinuing the flow of fluid under pressure to certain of said sequence valves for interrupting the operating cycle prior to operation of said wipers, and operator controlled means adapted to be engaged by the hands of the operator for actuating said cycle interrupting valve to re-

establish flow of fluid under pressure to said sequence valves thereby to continue said automatic operating cycle.

23. In a machine for shaping uppers over lasts, means for supporting a last in position for the shaping of an upper thereover, a plurality of fluid pressure operated means for pulling the upper in different locations around an end portion of the last, and a pair of fluid pressure operated wipers for wiping the lasting margin of the upper inwardly over an insole on said end portion of the last, a source of fluid under pressure, control valve means for initiating an operating cycle of the machine, a plurality of sequence valves for controlling the operation of said grippers and wipers in predetermined sequence in the course of an automatic operating cycle, a cycle interrupting valve associated with said sequence valves and adapted to be set for discontinuing the flow of fluid under pressure to certain of said sequence valves for interrupting the operating cycle, and operator controlled means comprising two control members located respectively at the opposite sides of said last supporting means and adapted to be engaged by the hands of the operator for actuating said cycle interrupting valve to reestablish flow of fluid under pressure to said sequence valves thereby to continue said automatic operating cycle.

24. In a machine for shaping uppers over lasts, means for supporting a last in position for the shaping of an upper thereover, a plurality of fluid pressure operated means for pulling the upper in different locations around an end portion of the last, and a pair of fluid pressure operated wipers for wiping the lasting margin of the upper inwardly over an insole on said end portion of the last, a source of fluid under pressure, control valve means for initiating an operator cycle of the machine, a plurality of sequence valves for controlling the operation of said grippers and wipers in predetermined sequence in the course of an automatic operating cycle, a cycle interrupting valve associated with said sequence valves and adapted to be set for discontinuing the flow of fluid under pressure to certain of said sequence valves for interrupting the operating cycle prior to operation of said wipers, and operator controlled means comprising two control members located respectively at the opposite sides of said last supporting means and adapted to be engaged by the hands of the operator for actuating said cycle interrupting valve to reestablish flow of fluid under pressure to said sequence valves thereby to continue said automatic operating cycle.

25. In a machine for shaping uppers over lasts, means for supporting a last in position for the shaping of an upper thereover, a plurality of fluid pressure operated grippers for pulling the upper in different locations around the toe end and forepart of the last including an end gripper for pulling the upper at the extreme toe end of the last; toe grippers for pulling the upper at the opposite sides of the toe portion of the last and forepart grippers for pulling the upper at the opposite sides of the forepart of the last, fluid pressure operated forepart wipers for wiping the lasting margin of the upper inwardly over the bottom of the forepart of an insole on the last, fluid pressure operated means for moving said toe and said forepart grippers inwardly into engagement with the last, a first control valve for causing such inward movement of said grippers by said moving means, a second control valve for initiating an operating cycle of said grippers and wipers, a plurality of sequence valves for controlling the operation of said grippers and wipers in predetermined sequence in the course of an automatic operating cycle, a cycle interrupting valve associated with said sequence valves and adapted to be set for discontinuing the flow of fluid under pressure to certain of said sequence valves for interrupting the operating cycle, and operator controlled means for actuating said cycle interrupting valve to reestablish flow of fluid under pressure

to said sequence valves thereby to continue said automatic operating cycle.

26. In a machine for shaping uppers over lasts, means for supporting a last in position for the shaping of an upper thereover, a plurality of fluid pressure operated grippers for pulling the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, fluid pressure operated forepart wipers for wiping the lasting margin of the upper inwardly over the bottom of the forepart of an insole on the last, fluid pressure operated means for moving said toe and said forepart grippers inwardly into engagement with the last, a first treadle actuated control valve for causing such inward movement of said grippers by said moving means, a second treadle operated control valve for initiating an operating cycle of said grippers and wipers, a plurality of sequence valves for controlling the operation of said grippers and wipers in predetermined sequence in the course of an automatic operating cycle, a cycle interrupting valve associated with said sequence valves and adapted to be set for discontinuing the flow of fluid under pressure to certain of said sequence valves for interrupting the operating cycle, and operator controlled means for actuating said cycle interrupting valve to reestablish flow of fluid under pressure to said sequence valves thereby to continue said automatic operating cycle.

27. In a machine for shaping uppers over lasts, means for supporting a last in position for the shaping of an upper thereover, a plurality of fluid pressure operated grippers for pulling the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, fluid pressure operated forepart wipers for wiping the lasting margin of the upper inwardly over the bottom of the forepart of an insole on the last, fluid pressure operated means for moving said toe and said forepart grippers inwardly into engagement with the last, a first treadle operated control valve for causing such inward movement of said grippers by said moving means, a second treadle operated control valve for initiating an operating cycle of said grippers and wipers, a plurality of sequence valves for controlling the operation of said grippers and wipers in predetermined sequence in the course of an automatic operating cycle, a cycle interrupting valve associated with said sequence valves and adapted to be set in response to operation of said first control valve for discontinuing the flow of fluid under pressure to certain of said sequence valves for interrupting the operating cycle prior to the operation of said forepart wipers, and operator controlled means for actuating said cycle interrupting valve to reestablish flow of fluid under pressure to said sequence valves thereby to continue said automatic operating cycle.

28. In a machine for shaping uppers over lasts, means for supporting a last in position for the shaping of an upper thereover, a plurality of fluid pressure operated grippers for pulling the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, fluid pressure operated forepart wipers for wiping the lasting margin of the upper inwardly over the bottom of the forepart of an insole on the last, fluid pressure operated means for moving said toe and said forepart grippers inwardly into engagement with the last, a first control valve for causing said inward movement of said

grippers by said moving means, a second control valve for initiating an operating cycle of said grippers and wipers, a plurality of sequence valves for controlling the operation of said grippers and wipers in a predetermined sequence in the course of an automatic operating cycle, a cycle interrupting valve associated with said sequence valves and adapted to be set for discontinuing the flow of fluid under pressure to certain of said sequence valves for interrupting the operating cycle, and operator controlled means adapted to be engaged by the hand of the operator for actuating said cycle interrupting valve to reestablish flow of fluid under pressure to said sequence valves thereby to continue said automatic operating cycle.

29. In a machine for shaping uppers over lasts, means
15 for supporting a last in position for the shaping of an upper
thereover, a plurality of fluid pressure operated grippers
for pulling the upper in different locations around the toe
end and forepart of the last including an end gripper for
pulling the upper at the extreme toe end of the last, toe
20 grippers for pulling the upper at the opposite sides of the
toe portion of the last and forepart grippers for pulling
the upper at the opposite sides of the forepart of the last,
fluid pressure operated forepart wipers for wiping the last-
ing margin of the upper inwardly over the bottom of the
25 forepart of an insole on the last, fluid pressure operated
means for moving said toe and said forepart grippers
inwardly into engagement with the last, a first treadle
operated control valve for causing such inward movement
of said grippers by said moving means, a second treadle
30 operated control valve for initiating an operating cycle
of said grippers and wipers, a plurality of sequence valves
for controlling the operation of said grippers and wipers
in a predetermined sequence in the course of an automatic
operating cycle, a cycle interrupting valve associated with
35 said sequence valves and adapted to be set for discontinuing
the flow of fluid under pressure to certain of said sequence
valves for interrupting the operating cycle, and operator
controlled means adapted to be engaged by the
hands of the operator for actuating said cycle interrupting
40 valve to reestablish flow of fluid under pressure to
said sequence valves thereby to continue the operating
cycle

cycle.

30. In a machine for shaping uppers over lasts, means for supporting a last in position for the shaping of an upper thereover, a plurality of fluid pressure operated grippers for pulling the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, fluid pressure operated forepart wipers for wipping the lasting margin of the upper inwardly over the bottom of the forepart of an insole on the last, fluid pressure operated means for moving said toe and said forepart grippers inwardly into engagement with the last, a first treadle operated valve for causing such inward movement of said grippers by said moving means, a second treadle operated valve for initiating an operating cycle of said grippers and wipers, a plurality of sequence valves for controlling the operation of said grippers and wipers in predetermined sequence in the course of an automatic operating cycle, a cycle interrupting valve associated with said sequence valves adapted to be set in response to operation of said first control valve for discontinuing the flow of fluid under pressure to certain of said sequence valves for interrupting the operating cycle, prior to the operation of said forepart wipers, and operator controlled means adapted to be engaged by the hands of the operator for actuating said cycle interrupting valve to reestablish flow of fluid under pressure to said sequence valves thereby to continue said automatic operating cycle.

31. In a machine for shaping uppers over lasts, means for supporting a last in position for the shaping of an upper thereover, a plurality of fluid pressure operated

grippers for pulling the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, fluid pressure operated forepart wipers for wiping the lasting margin of the upper inwardly over the bottom of the forepart of an insole on the last, fluid pressure operated means for moving said toe and said forepart grippers inwardly into engagement with the last, a first control valve for causing such inward movement of said grippers by said moving means, a second control valve for initiating an operating cycle of said grippers and wipers, a plurality of sequence valves for controlling the operation of said grippers and wipers in a predetermined sequence in the course of an automatic operating cycle, a cycle interrupting valve associated with said sequence valves and adapted to be set for discontinuing the flow of fluid under pressure to certain of said sequence valves for interrupting the operating cycle, and operator controlled means comprising two control members located respectively at the opposite sides of said last supporting means and adapted to be engaged by the hands of the operator for actuating said cycle interrupting valve to reestablish flow of fluid under pressure to said sequence valves thereby to continue said automatic operating cycle.

32. In a machine for shaping uppers over lasts, means for supporting a last in position for the shaping of an upper thereover, a plurality of fluid pressure operated grippers for pulling the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, fluid pressure operated forepart wipers for wiping the lasting margin of the upper inwardly over the bottom of the forepart of an insole on the last, fluid pressure operated means for moving said toe and said forepart grippers inwardly into engagement with the last, a first treadle operated control valve for causing such inward movement of said grippers by said moving means, a second treadle operated control valve for initiating an operating cycle of said grippers and wipers, a plurality of sequence valves for controlling the operation of said grippers and wipers in a predetermined sequence in the course of an automatic operating cycle, a cycle interrupting valve associated with said sequence valves and adapted to be set for discontinuing the flow of fluid under pressure to certain of said sequence valves for interrupting the operating cycle, and operator controlled means comprising two control members located respectively at the opposite sides of said last supporting means and adapted to be engaged by the hands of the operator for actuating said cycle interrupting valve to reestablish flow of fluid under pressure to said sequence valves thereby to continue said automatic operating cycle.

33. In a machine for shaping uppers over lasts, means for supporting a last in position for the shaping of an upper thereover, a plurality of fluid pressure operated grippers for pulling the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, fluid pressure operated forepart wipers for wiping the lasting margin of the upper inwardly over the bottom of the forepart of an insole on the last, fluid pressure operated means for moving said toe and said forepart grippers inwardly into engagement with the last, a first treadle operated valve for causing such in-

ward movement of said grippers by said moving means, a second treadle operated valve for initiating an operating cycle of said grippers and wipers, a plurality of sequence valves for controlling the operation of said grippers and wipers in predetermined sequence in the course of an automatic operating cycle, a cycle interrupting valve associated with said sequence valves adapted to be set in response to operation of said first control valve for discontinuing the flow of fluid under pressure to certain of said sequence valves for interrupting the operating cycle, prior to the operation of said forepart wipers, and operator controlled means comprising two control members located respectively at the opposite sides of said last supporting means and adapted to be engaged by the hands of the operator for actuating said cycle interrupting valve to reestablish flow of fluid under pressure to said sequence valve thereby to continue said automatic operating cycle.

34. In a machine for shaping uppers over lasts, means for supporting a last in position for the shaping of an upper thereover, a plurality of fluid pressure operated grippers for pulling the upper in different locations around an end portion of the last, and a pair of fluid pressure operated wipers for wiping the lasting margin of the upper inwardly over an insole on said end portion of the last, a source of fluid under pressure, control valve means for initiating an operating cycle of the machine, a plurality of sequence valves for controlling the operation of said grippers and wipers in predetermined sequence in the course of an automatic operating cycle, means under the control of said sequence valves for automatically returning said control valve means after the operation of said grippers and wipers thereby to complete the automatic operating cycle of the machine.

35. In a machine for shaping uppers over lasts, means for supporting a last in position for the shaping of an upper thereover, a plurality of fluid pressure operated grippers for pulling the upper in different locations around an end portion of the last, and a pair of fluid pressure operated wipers for wiping the lasting margin of the upper inwardly over an insole on said end portion of the last, a source of fluid under pressure, treadle operated control valve means for initiating an operating cycle of the machine, a plurality of sequence valves for controlling the operation of said grippers and wipers in predetermined sequence in the course of an automatic operating cycle, and means under the control of said sequence valves for automatically returning said control valve means after the operation of said grippers and wipers thereby to complete the automatic operating cycle of the machine.

36. In a machine for shaping uppers over lasts, means for supporting a last in position for the shaping of an upper thereover, a plurality of fluid pressure operated grippers for pulling the upper in different locations around an end portion of the last, and a pair of fluid pressure operated wipers for wiping the lasting margin of the upper inwardly over an insole on said end portion of the last, a source of fluid under pressure, control valve means for initiating an operating cycle of the machine, a plurality of sequence valves for controlling the operation of said grippers and wipers in predetermined sequence in the course of an automatic operating cycle, and fluid pressure operated means under the control of one of said sequence valves for automatically returning said control valve means after the operation of said grippers and wipers thereby to complete the automatic operating cycle of the machine.

37. In a machine for shaping uppers over lasts, means for supporting a last in position for the shaping of an upper thereover, a plurality of fluid pressure operated grippers for pulling the upper in different locations around the toe end and forepart of the last including an end gripper for pulling the upper at the extreme toe end of the last, toe grippers for pulling the upper at the oppo-

site sides of the toe portion of the last and forepart grippers for pulling the upper at the opposite sides of the forepart of the last, fluid pressure operated forepart wipers for wiping the lasting margin of the upper inwardly over the bottom of the forepart of an insole on the last, fluid pressure operated means for moving said toe and said forepart grippers inwardly into engagement with the last, a first control valve for causing such inward movement of said grippers by said moving means, a second control valve for initiating an operating cycle of the machine, a plurality of sequence valves for controlling the operation of said grippers and wipers in predetermined sequence in the course of an automatic operating cycle, and means under the control of said sequence valves for automatically returning said two control valves after the operation of said grippers and wipers thereby to complete the automatic operating cycle of the machine.

38. In a machine for shaping uppers over lasts, means for supporting a last in position for the shaping of an upper thereover, a plurality of fluid pressure operated grippers for pulling the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, fluid pressure operated forepart wipers for wiping the lasting margin of the upper inwardly over the bottom of the forepart of an insole on the last, fluid pressure operated means for moving said toe and said forepart grippers inwardly into engagement with the last, a first treadle operated control valve for causing such inward movement of said grippers by said moving means, a second treadle operated control valve for initiating an operating cycle of the machine, a plurality of sequence valves for controlling the operation of said grippers and wipers in predetermined sequence in the course of an automatic operating cycle, and means under the control of said sequence valves for automatically returning said two control valves after the operation of said grippers and wipers thereby to complete the automatic operating cycle of the machine.

39. In a machine for shaping uppers over lasts, means for supporting a last in position for the shaping of an upper thereover, a plurality of fluid pressure operated grippers for pulling the upper in different locations around the toe end and forepart of the last including an end gripper for pulling the upper at the extreme toe end of the last, toe grippers for pulling the upper at the opposite sides of the toe portion of the last and forepart grippers for pulling the upper at the opposite sides of the forepart of the last, fluid pressure operated forepart wipers for wiping the lasting margin of the upper inwardly over the bottom of the forepart of an insole on the last, fluid pressure operated means for moving said toe and said forepart grippers inwardly into engagement with the last, a first control valve for causing such inward movement of said grippers by said moving means, a second control valve for initiating an operating cycle of the machine, a plurality of sequence valves for controlling the operation of said grippers and wipers in predetermined sequence in the course of an automatic operating cycle, and fluid pressure operated means under the control of one of said sequence valves for automatically returning said two control valves after the operation of said grippers and wipers thereby to complete the automatic operating cycle of the machine.

40. In a machine for shaping uppers over lasts, means for supporting a last in position for the shaping of an upper thereover, a plurality of fluid pressure operated grippers for pulling the upper in different locations around the toe end and forepart of the last including an end gripper for pulling the upper at the extreme toe end of the last, toe grippers for pulling the upper at the opposite sides of the toe portion of the last and forepart

grippers for pulling the upper at the opposite sides of the forepart of the last, fluid pressure operated forepart wipers for wiping the lasting margin of the upper inwardly over the bottom of the forepart of an insole on the last, fluid pressure operated means for moving said toe and said forepart grippers inwardly into engagement with the last, a first treadle operated control valve for causing such inward movement of said grippers by said moving means, a second treadle operated control valve for initiating an operating cycle of the machine, a plurality of sequence valves for controlling the operation of said grippers and wipers in predetermined sequence in the course of an automatic operating cycle, and fluid pressure operated means under the control of one of said sequence valves for automatically returning said two control valves after the operation of said grippers and wipers thereby to complete the automatic operating cycle of the machine.

41. In a machine for shaping uppers over lasts, means for supporting a last in position for the shaping of an upper thereover, a plurality of grippers for pulling the upper in different locations around the toe end and forepart of the last, a pair of wipers for wiping the lasting margin of the upper over an insole on the last, a heel rest movable into engagement with the upper at the heel end of the last for holding the last against movement during the operation of said grippers and wipers, means for moving said heel rest from an idle position spaced from the last into an operative position in engagement with the upper at the heel end of the last, means for locking said heel rest in its operative position, and a member carried by said heel rest and movable relatively thereto during movement of the heel rest into its operative position for actuating said locking means.

42. In a machine for shaping uppers over lasts, means for supporting a last in position for the shaping of an upper thereover, a plurality of grippers for pulling the upper in different locations around the toe end and forepart of the last, a pair of wipers for wiping the lasting margin of the upper over an insole on the last, a heel rest movable into engagement with the upper at the heel end of the last for holding the last against movement during the operation of said grippers and wipers, fluid pressure operated means for moving said heel rest from an idle position spaced from the last into an operative position in engagement with the upper at the heel end of the last, means for locking said heel rest in its operative position, and a member carried by said heel rest and movable relatively thereto during movement of the heel rest into its operative position for actuating said locking means.

43. In a machine for shaping uppers over lasts, means for supporting a last in position for the shaping of an upper thereover, a plurality of grippers for pulling the upper in different locations around the toe end and forepart of the last, a pair of wipers for wiping the lasting margin of the upper over an insole on the last, a heel rest movable into engagement with the upper at the heel end of the last for holding the last against movement during the operation of said grippers and wipers, means for moving said heel rest from an idle position spaced from the last into an operative position in engagement with the upper at the heel end of the last, mechanical means for locking said heel rest in its operative position, and a member carried by said heel rest and movable relatively thereto during movement of the heel rest into its operative position for actuating said locking means.

44. In a machine for shaping uppers over lasts, means for supporting a last in position for the shaping of an upper thereover, a plurality of grippers for pulling the upper in different locations around the toe end and forepart of the last, a pair of wipers for wiping the lasting margin of the upper over an insole on the last, a heel rest movable into engagement with the upper at the heel end of the last for holding the last against movement

during the operation of said grippers and wipers, fluid pressure operated means for moving said heel rest from an idle position spaced from the last into an operative position in engagement with the upper at the heel end of the last, mechanical means for locking said heel rest in its operative position, and a member carried by said heel rest and movable relatively thereto during movement of the heel rest into its operative position for actuating said locking means.

45. In a machine for shaping uppers over lasts, means for supporting a last in position for the shaping of an upper thereover, a plurality of grippers for pulling the upper in different locations around the toe end and forepart of the last, a pair of wipers for wiping the lasting margin of the upper inwardly over an insole on the last, an abutment adjacent to said supporting means for engaging the toe end of the last to determine the lengthwise position of the last relatively to said grippers and wipers, a V-shaped heel rest movable into engagement with the upper at the heel end of the last for locating the heel end of the last laterally in relation to said grippers and wipers, means for moving said heel rest from an idle position spaced from the last into an operative position in engagement with the upper at the heel end of the last, means for locking said heel rest in its operative position, and a member carried by said heel rest and movable relatively thereto during movement of the heel rest into its operative position for actuating said locking means.

46. In a machine for shaping uppers over lasts, means for supporting a last in position for the shaping of an upper thereover, a plurality of grippers for pulling the upper in different locations around the toe end and forepart of the last, a pair of wipers for wiping the lasting margin of the upper inwardly over an insole on the last, an abutment adjacent to said supporting means for engaging the toe end of the last to determine the lengthwise position of the last relatively to said grippers and wipers, a V-shaped heel rest movable into engagement with the upper at the heel end of the last for locating the heel end of the last laterally in relation to said grippers and wipers, fluid pressure operated means for moving said heel rest from an idle position spaced from the last into an operative position in engagement with the upper at the heel end of the last, means for locking said heel rest in its operative position, and a member carried by said heel rest and movable relatively thereto during movement of the heel rest into its operative position for actuating said locking means.

47. In a machine for shaping uppers over lasts, means for supporting a last in position for the shaping of an upper thereover, a plurality of grippers for pulling the upper in different locations around the toe end and forepart of the last, a pair of wipers for wiping the lasting margin of the upper inwardly over an insole on the last, an abutment adjacent to said supporting means for engaging the toe end of the last to determine the lengthwise position of the last relatively to said grippers and wipers, a V-shaped heel rest movable into engagement with the upper at the heel end of the last for locating the heel end of the last laterally in relation to said grippers and wipers, means for moving said heel rest from an idle position spaced from the last into an operative position in engagement with the upper at the heel end of the last, mechanical means for locking said heel rest in its operative position, and a member carried by said heel rest and movable relatively thereto during movement of the

heel rest into its operative position for actuating said locking means.

48. In a machine for shaping uppers over lasts, means for supporting a last in position for the shaping of an upper thereover, a plurality of grippers for pulling the upper in different locations around the toe end and forepart of the last, a pair of wipers for wiping the lasting margin of the upper inwardly over an insole on the last, an abutment adjacent to said supporting means for engaging the toe end of the last to determine the lengthwise position of the last relatively to said grippers and wipers, a V-shaped heel rest movable into engagement with the upper at the heel end of the last for locating the heel end of the last laterally in relation to said grippers and wipers, fluid pressure operated means for moving said heel rest from an idle position spaced from the last into an operative position in engagement with the upper at the heel end of the last, mechanical means for locking said heel rest in its operative position, and a member carried by said heel rest and movable relatively thereto during movement of the heel rest into its operative position for actuating said locking means.

49. In a machine for shaping uppers over lasts, means for supporting a last in position for the shaping of an upper thereover, means for pulling the upper over the last comprising a gripper having a pair of jaws and mounted for movement from a remote and inoperative position in a direction extending heightwise of the last to an operative position adjacent to the last, means for thus moving said gripper, and means adapted to engage the lasting margin of the upper as the gripper is moved from said inoperative to said operative position and to deflect the lasting margin of the upper into a position to be received between the jaws of said gripper.

50. In a machine for shaping uppers over lasts, means for supporting a last in position for the shaping of an upper thereover, means for pulling the upper over the last including a gripper having a pair of jaws mounted for movement from a remote and inoperative position in a direction extending heightwise of the last to an operative position adjacent to the last, means for thus moving said gripper, and a finger adapted to engage the lasting margin of the upper as said gripper is moved from said inoperative to said operative position and to deflect the lasting margin of the upper into a position to be received between the jaws of said gripper.

51. In a machine for shaping uppers over lasts, means for supporting a last in position for the shaping of an upper thereover, means for pulling the upper over the last comprising a gripper having a pair of jaws and mounted for movement from a remote and inoperative position in a direction extending heightwise of the last to an operative position adjacent to the last, means for thus moving said gripper, and a spring operated finger associated with each of said grippers and adapted to engage the lasting margin of the upper as the gripper is moved from said inoperative to said operative position and to deflect the lasting margin of the upper into a position to be received between the jaws of said gripper.
